TELEPHONE SYSTEM

John Wicks, Oak Park, Ill., assignor to Associated Electric Laboratories, Inc., Chicago, Ill., a corporation of Delaware

Application November 7, 1934, Serial No. 751,805

22 Claims. (Cl. 179—16)

The present invention relates to telephone systems in general, but is concerned more particularly with telephone systems in which automatic switches are employed in setting up connections. 5 The broad general object of the invention may be stated to be the provision of new and improved controlling or dialling arrangements for use in a telephone system wherein automatic switching apparatus is controlled over an inter-exchange trunk line or talking circuit. 10

General description

It has long been recognized that the satisfactory controlling of the various functions peculiar to 15 the operation and control of automatic switches over inter-exchange trunk lines is a special problem apart from the problem of controlling the automatic switching apparatus in an exchange over subscribers' lines local to such exchange. 20 Inter-exchange trunk lines as referred to herein should not be confused with inter-office trunk lines used in multi-office telephone systems to interconnect the various offices into which an exchange may be divided. The inter-exchange trunk lines 25 referred to herein are those which connect the exchange of one city or village with the exchange of another city or village, which exchanges may therefore be many miles apart.

A trunk line that interconnects two exchanges separated by a considerable distance represents a sizeable financial outlay, as is well known. It has long been a practice, therefore, to economize as much as possible in the use of the conductors interconnecting two exchanges, one widely used 30 measure of economy involving the use of a so-called phantom circuit by means of which a third talking circuit is obtained by the proper association of two physical circuits. In addition, the return on the investment has been increased substantially in many cases by using the conductors of the physical circuits separately, as single conductor telegraph lines or other lines over which telegraphic or similar signals are to be transmitted. Telephone lines so arranged are sometimes referred to as composed lines, and the conductors leading therefrom over which the telegraphic impulses pass are referred to as the composite legs. 40

With the foregoing explanation in mind, it will 45 readily be understood that the usual loop impulses over the talking conductors of a trunk line, as employed locally in automatic exchanges, is not suitable for use over a talking circuit extending by way of trunk line conductors from one exchange to another exchange located some dis-

tance away. In the present invention, the problem presented has been attacked along the line of providing suitable impulse transmitting and receiving equipment at either end of an inter-exchange trunk line or talking circuit for transmitting switch controlling and other necessary impulses as impulses of alternating current which pass over a talking circuit in the same manner as the impulses of voice current pass over the talking circuit during conversation. 5

One feature of the system disclosed herein is that the automatic switching apparatus in the distant exchange is made ready for operation responsive to a seizing impulse transmitted over the talking circuit when the trunk line is seized; the 15 series of setting impulses (the impulses which bring about the desired positioning of the automatic switches) are transmitted as series of impulses of alternating current; the supervisory signals, which are necessary to indicate the removal 20 of the receiver of the called line and the subsequent replacement of the receiver on the called line after conversation, are controlled by a single impulse of alternating current transmitted from the called exchange back over the inter-exchange 25 talking circuit to the calling exchange when the receiver is removed and another single impulse of alternating current when the receiver is subsequently replaced; and the release of the automatic 30 switches in the called exchange is brought about responsive to the prolonged impulse of alternating current transmitted over the talking circuit from the calling exchange to the called exchange. 35

When such a system of controlling the setting up, supervision, and release of automatic connections is employed, a special problem which arises is the one of preventing the operation of the responsive devices in either the called exchange or the calling exchange responsive to voice currents during conversation, and to other 40 currents of a transitory nature; a false operation of one of the receiving signal devices would often occur and result in a false or misleading operation of the supervisory apparatus or even possibly in a premature release of the connection if special provisions were not made to fore- 45 stall this.

It has also been found that the presence or absence of voice-current repeaters in a talking circuit between two exchanges, being determined 50 generally according to the length or transmission qualities of the circuit, must be taken into consideration, for example in the selection of a frequency of alternating current to be used in the transmission of the necessary impulses. 55

It has been determined by experimentation that 60-cycle alternating current impulses may be used satisfactorily over either physical or phantom inter-exchange circuits provided the physical circuits are not composited for telegraph or similar use, in which case 120-cycle impulses are much more satisfactory.

When voice-current repeaters are included in the inter-exchange circuits, the frequency and voltage limitations of the voice-current repeaters commonly used are such that a higher frequency, 1000-cycles, for example, must be employed for satisfactory signalling.

When the 60-cycle or 120-cycle arrangement is used there seems to be no special problem involved in preventing the voice currents from falsely affecting or operating the receiving signal devices. But, when a frequency well within the voice range is required on account of the inclusion of a voice current repeater in the circuit, special provisions must be made to keep the voice currents and other transitory surges or impulses from affecting the receiving signal devices. This problem is met by transmitting a carrier current of a frequency (1000-cycles for example) well within the voice range and by modulating this carrier current by means of a lower frequency (60-cycles for example), and by arranging the signal receiving apparatus so that it will respond only to a current at the carrier frequency modulated by the determined modulating frequency. The receiving arrangement is such that it will not respond to the two frequencies when one is merely superimposed on the other, but the carrier frequency must be actually modulated by the lower frequency current, which condition does not obtain during conversation, as will be understood. The arrangements of the receiving apparatus have been devised for responding to the carrier current when received in impulses for switch setting purposes, and to respond selectively to the carrier current when modulated for signal purposes. In one arrangement, a combination of relays is employed which, by virtue of their operating and releasing characteristics, will respond one way when the carrier current is being received in impulses corresponding to the frequency of impulses used to position the automatic switches, and will respond in another way when carrier current modulated at the signal frequency is received. The other arrangement which has been devised for separating the signal impulses from the switch setting impulses makes use of a receiving circuit tuned to the modulating signalling current. This tuned circuit includes a signal relay which is not affected by voice currents during conversation and which is not affected by the switch-setting impulses, but which responds reliably each time the carrier current modulated at the signal frequency is received.

At this point it may be mentioned that the salient features of the invention disclosed herein, although shown and described in connection with a telephone system in which the setting of the switches in a distant exchange are controlled by calling subscribers in the originating exchange, are applicable to systems in which inter-exchange calls are completed under the control of a switchboard operator who is provided with means for controlling the positioning of the automatic switches in a distant exchange.

The foregoing objects and features of the invention, together with other objects and features not specifically mentioned, will become more ap-

parent upon a further perusal of the specification.

Description of drawings

Referring now to the accompanying drawings comprising Figs. 1 to 4, they show by means of the usual circuit diagrams a sufficient amount of the apparatus involved in a system embodying the features of the invention to enable the invention to be understood.

Fig. 1 is an inter-exchange trunking diagram showing how calls may be completed between three interconnected exchanges, A, B, and C.

Fig. 2 shows the circuit equipment associated with one end of an inter-exchange trunk line or talking circuit on which no voice-current repeaters are used, being adaptable for 60-cycle operation (used when the trunk line is not composited) and 120-cycle operation (used when the trunk line is composited).

Fig. 3 shows the equipment associated with one end of an inter-exchange trunk line supplied with a voice-current repeater. In Fig. 3, the apparatus for responding selectively to the signal impulses includes a group of relays which respond selectively by virtue of their operating and release characteristics.

Fig. 4 shows a modification of the arrangement of Fig. 3, wherein the incoming-signal relay is included in a circuit tuned to the signal frequency.

Trunking arrangement

Referring now particularly to Fig. 1, the exchanges A and B are assumed to be located sufficiently far from each other that a voice-current repeater station is required, while exchange B is located somewhat nearer to exchange C, so that the transmission qualities of the trunk lines between exchanges B and C are such that voice current repeaters are not required. Exchange B is the tandem switching point as regards exchanges A and C, so that all calls from either of the outlying exchanges to the other passes through exchange B.

The group of trunk lines or talking circuits interconnecting exchanges A and B is represented by the trunk line or talking circuit TL1, extending from the impulse repeater IR1 in exchange A to impulse repeater IR2 in exchange B, by way of a repeater station, while the group of trunk lines or talking circuits interconnecting exchanges B and C is represented by the trunk lines or talking circuit TL2, extending from impulse repeater IR3 in exchange B to impulse repeater IR4 in exchange C. It will be understood, of course, that a sufficient number of trunk lines in either inter-exchange group is provided to meet the traffic requirements. Each of these trunk lines is equipped for two-way telephonic operation, that is, each of the impulse repeaters IR1 to IR4 is a two-way repeater. The trunk line TL1, it will be noted, passes through the voice-current repeater VCR in the repeater station. This voice-current repeater is assumed to be of the usual construction, wherein a vacuum-tube or similar apparatus is employed to restore attenuated voice currents to satisfactory values.

Each of the exchanges A, B, and C is assumed to be serving at present a few hundred lines. Therefore, a local connection from one subscriber's line to another passes through a hundreds selector and a connector. In exchange A, one substation, SS1, is shown associated with a line terminating at the exchange in the line switch LS1. The lineswitch LS1 has access to

Calls from exchange B to exchange A

a group of hundreds selectors, of which the selector S2 is one. The selector S2 has access to a number of groups of connectors, the connector C1 of the second group being indicated, as is the connector C2 in the third group. The inter-exchange trunk lines such as the trunk line TL1 are reached through the tenth level of the selectors such as S2, by way of the impulse repeaters such as IR1. Each of the trunk lines, such as TL1, has an incoming selector, such as S1, associated therewith through the impulse repeater, such as IR1.

The arrangement in exchange B is similar to that described in exchange A, local substations SS2 and SS3 being shown in association with lines terminating respectively in the line switches LS2 and LS3. The line switches have common access to a group of selectors, such as the selector S3, and the selectors have access through their various levels to groups of connectors, such as the connectors C3 and C4, representing the third- and second-level groups, respectively. The connector C3 has access to the line of substation SS3, and the connector C4 has access to the line of substation SS2.

Incoming selector S4 is individual to the trunk line TL1 interconnecting exchanges A and B, while the incoming selector S5 is individual to the trunk line TL2, interconnecting the exchanges B and C.

The trunk lines extending to exchange A are reached by way of the tenth level of the selectors, while the trunk lines extending from exchange B to exchange C are reached by way of the ninth level of the selectors.

In exchange C, selector S6, accessible to the line switch LS4 of the local substation SS4, is representative of the group of local selectors, while the selector S7, individual to the trunk line TL2, represents the group of incoming selectors. The connectors C5 and C6 represent the third and hundreds groups, respectively, the connector C5 having access to the line of substation SS4. Although the above explained trunking arrangements follow established practice, explanation will be given at this point to facilitate a ready understanding of circuit operations to be later described.

50 *Local calls in exchange B*

The way in which local connections are completed in exchange B will first be explained. For this purpose it will be assumed that the subscriber at substation SS2 desires to obtain connection with the subscriber at substation SS3. For this purpose, the subscriber at substation SS2 removes his receiver, whereupon the line-switch LS2 operates in the well-known manner to select an idle selector, the selector S3, for example. The selector S3 is thereupon prepared for operation, and it responds to the first digit in the desired number (the digit 3 in this case) to select an idle trunk line extending from the third level of its bank contacts, the trunk line extending to the connector C3, for example.

Upon seizure, the connector C3 is prepared for operation in the usual manner, and it responds to the two final digits in the number (the digits 2 and 0, for example) to extend the connection to the desired line, the line of substation SS3.

The established connection is released in the usual manner when the subscriber at substation SS2 replaces his receiver.

Assume now that the subscriber at substation SS2, exchange B, desires to converse with the subscriber at SS1, exchange A. Under this condition, the subscriber at substation SS2 removes his receiver and dials the listed number of the subscriber at substation SS1, preceded by the digit 0, assigned to exchange A when called from exchange B. Assuming that the selector S3 is the one seized by the lineswitch LS2 when the receiver is removed at substation SS2, this selector responds to the digit 0 by selecting an idle trunk line extending from the tenth level of its bank contacts, the trunk line extending by way of the impulse repeater IR2 to the inter-exchange trunk line TL1, for example. When this trunk line is seized, the impulse repeaters IR2 and IR1 are prepared for operation, and, through the response of the repeater IR2, the incoming selector S1 in exchange A is prepared for operation.

When the first digit in the listed number of the subscriber at substation SS1 is now called, the selector S1 responds by selecting an idle trunk line extending to a connector, such as the connector C2, having access to the line of substation SS1. The connector C2 may then respond to the two final digits of the number and extend the connection to the line of substation SS1.

The established connection is released when the calling subscriber at substation SS2 replaces his receiver.

Calls from exchange A to exchange B

When a subscriber of exchange A desires to establish connection with the line of a subscriber of exchange B, the substations SS1 and SS2 being assumed to be the ones involved, the connection is extended by way of the line switch LS1 to a selector such as S2, and may be further extended by way of the tenth level of the selector S2 and the impulse repeater IR1 to the inter-exchange trunk line TL1, whence it extends by way of the impulse repeater IR2 and the voice-current repeater VCR to the incoming selector S4. The selector S4 responds to the first digit in the listed number of the desired subscriber at substation SS2 and selects an idle connector, such as the connector C4, which responds to the two final digits in the number to complete the connection.

Inter-exchange calls between exchanges B and C

Inter-exchange calls may be completed between subscribers in exchange B and subscribers in exchange C in a manner similar to that described. For example, a connection set up from the line of substation SS2 of exchange B to the line of substation SS4 in exchange C includes the line switch LS2, and may include the selector S3, operated to the ninth level, the impulse repeater IR3, trunk line TL2, impulse repeater IR4, incoming selector S7 and the connector C5. To complete this connection, the listed number of the subscriber at substation SS4 is dialled, preceded by the digit 9.

An inter-exchange call from the line of substation SS4, exchange C, to the line of substation SS3, exchange B, includes the line switch LS4, and may include the selector S6, operated to the tenth level, the repeaters IR4 and IR3 between which the trunk line TL2 extends, the incoming selector S5, and the connector C3. To complete this connection, the subscriber at substation SS4 dials the listed number of the sub-

scriber at substation SS3, preceded by the digit 0.

Tandem calls between exchanges A and C

A call from exchange A to exchange C is switched through exchange B, and it may be set up in a manner now to be described: In case the calling subscriber is the one at substation SS1 and the called subscriber is the one at substation SS4, the connection includes the line switch LS1, and may include the local selector S2, operated to the tenth level, the repeaters IR1 and IR2, interconnected by the trunk line TL1, the incoming selector S4, operated to its ninth level, impulse repeaters IR3 and IR4, interconnected by the trunk line TL2, and the incoming selector S1, as well as the connector C5. In order to establish this connection, the subscriber at substation SS1 dials the listed local number of the line of the subscriber at substation SS4, preceded by the digit 0, indicating the exchange C, and the digit 9, indicating the exchange B.

Assume now that the subscriber at substation SS4 desires to converse with the subscriber at substation SS1, the established connection must be trunked through the exchange B to the exchange A. The connection includes the line switch LS4 and may include the local selector S6, the repeaters IR4 and IR3, interconnected by the trunk line TL2, the incoming selector S5, the repeaters IR2 and IR1, interconnected by the trunk line TL1, and the incoming selector S1, as well as the connector C2. To establish this connection, the subscriber at substation S4 dials the local listed number of the line of substation SS1, preceded by the digit 0, indicating the exchange B, and the further digit 0, indicating the exchange A.

Detailed description

The system having been described with relation to the trunking diagram given in Fig. 1, further consideration will now be given to the circuit drawings, Figs. 2, 3, and 4. These drawings, of course, are to be considered in connection with the trunking diagram of Fig. 1; similar parts appearing in the circuit drawings have the same reference characters applied as have the corresponding parts in Fig. 1.

Fig. 2 illustrates the impulse repeater IR3 which is located in exchange B and associated with one end of the trunk line TL2 extending between exchanges B and C. Since the trunk line TL2, according to the previous assumption, is not of sufficient length or of sufficient voice-attenuating characteristics to require the use of a voice-current repeater, a relatively simple impulse and signal circuit can be used between the impulse repeaters IR3 and IR3. Since the repeater IR4 may be identical in circuit arrangement with the repeater IR3, illustrated in Fig. 2, the repeater IR4 is not illustrated in detail. The equipment shown in the upper right-hand corner of Fig. 2, part 2, and arranged to be connected up alternatively, as indicated by the dotted jumper connections, is to be used in place of the impulse repeating relay 226 when 120-cycle signalling current, in place of 60-cycle signalling current, is used on account of the associated talking circuit including a composited line.

Call from SS2, exchange B to SS4, exchange C

The detailed description will include first a description of Fig. 2, with reference to the trunking diagram shown in Fig. 1. For this purpose it

will be assumed first that the subscriber at substation SS2, Figs. 2 and 1, whose line terminates in exchange B, desires to converse with the subscriber at substation SS4, Fig. 1, whose line terminates in exchange C.

As before described, the subscriber at substation SS2, in order to complete the connection removes his receiver and dials the local listed number of the subscriber at substation SS4, exchange C, preceded by the digit 9, assigned to 10 exchange B.

When the receiver (not shown) is removed at substation SS2, the line switch LS2 is caused to operate in the usual manner in search of an idle line. It will be assumed that the trunk line extending to the selector S3 is the first one found to be idle and is therefore seized. Under this condition, the selector S3 is separated for operation in the usual manner, and it responds to the exchange digit 9 by raising its wipers opposite the ninth level of bank contacts and searching for an idle trunk line extending to exchange C. Assuming that the trunk line comprising conductors 261, 262, and 263, and extending to exchange C by way of the impulse repeater IR3 and trunk line TL2, is the first one found to be idle, this trunk line is seized and connection to conductors 261, 262, and 263 is made in the usual manner.

As is well known, a standard automatic selector is arranged to place a ground potential momentarily upon the test wiper thereof upon seizing an idle trunk line. This ground potential is extended over the release-trunk conductor or test conductor 262 to the impulse repeater IR3, closing a circuit through the upper armatures of relays 218 and 220, by way of conductor 264, and through contacts of supervision-control relay 212 to the upper winding of shunt-control relay 213. Relay 213 is provided for the purpose of controlling the shunt connections around the associated repeating-coil windings. In order to prevent delay slightly the operation of relay 213, the second winding of the relay is normally closed through the inner-lower contacts of the relay, 45 forming a retarding winding. Upon operating, relay 213 at its upper and lower armatures opens shunt circuits which are normally closed around the left-hand repeating-coil windings, and it shunts the resistance element 270 so as to remove it from the talking circuit.

Line relay 203, connected to the incoming line conductors 261 and 263 by way of contacts of the answering-supervisory relay 202, operates over the calling subscriber's line when the impulse repeater is seized. At its inner armature, line relay 203 closes a circuit for the slow-acting release relay 204. Relay 204 operates and places ground potential at its upper armature on the release trunk conductor 262 so as to maintain the connection established through the selector S3 and the line switch LS2, and to maintain the shunt-control relay 213 in operated condition. At its lower armature, release relay 204 opens a point in the circuit of the incoming answering-supervisory relay 210, and at its inner upper armature it closes a circuit through armature 243 of the selector-seizing relay for cut-through relay 205.

Cut-through relay 205 now operates and extends the incoming talking conductors 261 and 263 through to the left-hand repeating coil windings; at its inner upper armature it disconnects the armature of the impulse-receiving relay 226 from the selector-seizing relay 208 and transfers

it to the outgoing answering-supervisory relay 202; it prepares a circuit at its inner lower armature for the outgoing series relay 218; and at its lower armature it closes a circuit by way of the inner upper armature and resting contact of pulse-timer relay 217 and conductor 266 for the preparing relay 214, so as to start into operation the relay devices necessary to transmit a seizing impulse over the trunk line TL2 to cause the distant impulse repeater IR4, Fig. 1, to be prepared for incoming operation.

Transmitting the seizing impulse

Upon operating, preparing relay 214 disconnects the talking conductors outgoing to the trunk line TL2 from the associated repeating-coil windings and extends them through the upper and lower windings of the retard coil 215 to the armatures of the dial-out relay 216; it grounds the free terminals of the filter condensers 256 and 259; and at its lower armature it grounds conductor 267, thereby closing a circuit through contacts of the pulse timer relay 217 and over conductor 268 for the dial-out relay 216. Relay 216 thereupon operates and closes the associated 60-cycle leads through the windings of the retard coil 215 to the talking conductors of the trunk line TL2. This operation, it is to be understood, is for the purpose of transmitting a 60-cycle impulse to the distant repeater IR4, Fig. 1, to prepare it for incoming operation in a manner which will be described subsequently in connection with the repeater IR3.

The dial-out relay 216 also extends the now grounded conductor 268 by way of conductor 269 and contacts of the outgoing series relay 218 to the winding of the pulse-timer relay 217. Relay 217, being provided with a copper collar on the armature end of its core, as indicated by the solid-black upper portion of the relay, is slow to operate so as to allow time for the impulse to be transmitted over the trunk line TL2.

At the end of a slight interval, pulse-timer relay 217 operates and closes a locking circuit for itself at its inner armature to ground through the lower armature of the operated cut-through relay 205, at the same time opening the circuit of the preparing relay 214 and opening its own initial circuit. Relay 217 also opens the circuits of dial-out relay 216 at its lower armature. As a result, relays 214 and 216 now restore and the 60-cycle seizing impulse transmitted over the trunk line TL2 is now terminated.

Dialling the number of the desired line

The subscriber at substation SS2, having dialled the digit 9, assigned to exchange C, with results as described, now dials the first digit in the number locally assigned in exchange C to the line of the desired substation SS4, Fig. 1. When this digit is dialled, each interruption produced in the calling line by the usual calling device (not shown) results in a momentary deenergization of line relay 203. Each time it deenergizes, line relay 213 momentarily opens the holding circuit of the slow-acting release relay 204 and it closes a circuit through contacts of the operated cut-through relay 205 for the slow-releasing outgoing series relay 218. As a result, relay 218 immediately operates and remains operated throughout the series of impulses, because of its slow releasing characteristics. Upon operating, relay 218 disconnects the incoming release trunk conductor 262 from the winding of shunt-control relay 213 and connects it to ground at an additional point,

thereby insuring the holding up of the connection established through the repeater even though slow-acting release relay 204 should chatter or tend to release momentarily during impulses. Shunt-control relay 213 is, therefore, restored 5 during the receipt of the series of impulses. With relay 216 restored, the upper left-hand repeating coil winding is directly shunted, and a shunt is placed around the lower left-hand repeating coil winding which includes resistor 271 10 and the upper winding of supervision control relay 212. With relay 213 restored, the condenser associated with the left-hand repeating coil windings is, in effect, bridged directly across the incoming talking conductors in series with the resistor 270, which condition has been found to be very satisfactory in assisting the line relay 203 in following the dial control exercised over calling lines of various characteristics.

Outgoing series relay 218, at its inner upper 20 armature, opens a point in the circuit of the incoming series relay 220 so as to prevent operation of relay 220 at this time. At the same time, relay 218 places a ground potential on conductor 266, so as to bring about an operation of the impulse 25 preparing relay 214 for the duration of the series of impulses. Since impulse timer relay 217 has become operated and locked as described, the operation of preparing relay 214 does not affect the dial-out relay 216 at this time. 30

With the outgoing series relay 218 operated, each momentary deenergization of line relay 203 results in the closure of a circuit at the lower armature of the line relay and through the inner lower armature of relay 218 for the two-way 35 repeating relay 212. Relay 212 therefore responds momentarily to each of the impulses in the series.

Impulse correction

The over-all result of the operations now to be 40 described is that for each operation of the repeating relay 212 a corrected impulse is delivered under the control of the relays at retard coils 221-225 to the dial-out relay 216.

Operation of impulse corrector under normal conditions

In explaining the operation of the impulse corrector, composed of relays 221, 223, and 225 the assumption will be made first that the calling device on the calling line is adjusted to operate at the normal speed (delivering usually ten impulses a second) and that the line of substation SS2 is of average characteristics so that line relay 203 follows the contacts of the calling device 50 correctly and therefore delivers the impulses at the same ratio as fixed in the calling device (preferably a sixty per cent break period, with a forty per cent make period between successive break 55 periods).

Under the conditions assumed, the operation is as follows: when repeating relay 219 operates, it locks itself at its lower armature through contacts of the pulse-lock relay 221, and it closes a 65 circuit at its inner upper armature through the retard coil 222 for the lower winding of the pulse timer relay 223. The operation of pulse timer relay 223 is delayed in two ways; (1) the building up of current through the lower winding of relay 70 223 is delayed by the inclusion of the retard coil 322 in its circuit, and (2) the upper winding of relay 223 is included in a closed circuit through contacts of the relay, having therefore a retarding effect upon the building up of the flux 75

through the magnetic structure of the relay. The adjustment of the relay is preferably such that the relay operates about four-tenths of an impulse cycle after its circuit is closed, which is two-tenths of an impulse cycle (under the assumed condition) before the repeating relay 219 restores responsive to the opening of its circuit by line relay 203 when the latter relay reoperates. Moreover, the time of operation of pulse-timer relay 223 is six-tenths of an impulse cycle before the next reoperate time of the repeating relay 219.

When the pulse timer relay 223 operates, it closes a circuit at its lower armature through the inner lower armature of the unoperated incoming series relay 228 and over conductor 268 for the dial-out relay 216. Relay 216 thereupon operates and starts the first repeated dial impulse over the trunk line TL2 from the 60-cycle supply through the retard coil 215 and contacts of the operated preparing relay 214.

At its upper armature, relay 223 closes a circuit for the pulse-lock relay 221, whereupon relay 221 operates and prepares a locking circuit for itself at its upper armature, while at its inner lower armature it closes a circuit for the pulse-timer relay 225 through the retard coil 224, at the same time unlocking the repeating relay 219 so as to permit this relay to restore now as soon as the dial impulse being delivered to it is terminated.

The pulse-timer relay 225 has delay provisions similar to those set forth in connection with the pulse timer relay 223 and it has a similar adjustment as regards its operating time. Relay 225 therefore does not operate immediately.

At its lower armature, the pulse lock relay 221 closes a parallel circuit for dial-out relay 216 through contacts of relay 220, so as to maintain relay 216 operated over conductor 268 after the pulse timer relay 223 has restored.

When the repeating relay 219 restores (six-tenths of an impulse cycle after it operated, under the assumed conditions) upon the reoperation of line relay 203, it opens the circuit of pulse-timer relay 222 and closes a locking circuit for pulse-lock relay 221 through the middle upper armature of pulse-timer relay 225 and the inner upper armature of the operated pulse-lock relay 221. As a result, the pulse-timer relay 223 immediately restores (two-tenths of an impulse cycle after it operated) and opens the initial circuit of the pulse lock relay 221 as well as the initial circuit of the dial-out relay 216. Relay 221 does not restore, however, for the time being because of the before-mentioned locking circuit, and dial-out relay 216 remains operated through the lower contacts of relay 221.

At the beginning of the second impulse cycle, two things occur simultaneously: (1) repeating relay 219 reoperates responsive to the second de-energization of line relay 203, and (2) pulse-timer relay 225 operates because four-tenths of an impulse cycle have elapsed since its circuit was closed by the pulse-lock relay 221 responsive to the operation of the pulse-timer relay 223. The locking circuit of the pulse-lock relay 221 is therefore opened at two points, and relay 221 restores as a result and opens the circuit of dial-out relay 216 at its lower armature, at the same time opening the circuit of pulse-timer relay 225 at its inner lower armature and reestablishing the locking circuit of the now reoperated repeating relay 219.

The dial-out relay 216 having been operated

under the control of the impulse corrector for a period of time corresponding to six-tenths of a normal impulse cycle, now restores to terminate the first 60-cycle dialling impulse transmitted over the trunk line TL2.

With the repeating relay 219 reoperated, the operations described before are repeated.

When the final impulse of the series has been transmitted, repeating relay 219 does not re-operate, but the restoration of the pulse lock relay 221 and the described termination of the impulse takes place when the pulse timer relay 225 operates, which takes place at the same time that the reoperation of relay 219 would have taken place had the series contained another impulse. 15

Correcting short impulses at normal frequency

Assume now that the calling device at the calling substation is operating at the normal speed and therefore generating impulses at the normal speed and ratio, but that the characteristics of the calling line are such that line relay 203 does not restore quickly enough responsive to an interruption in its circuit. Under this condition the impulses delivered to repeating relay 219 are 25 shorter than normal, although the time measured from the beginning of one impulse to the beginning of the next is the time of the normal impulse cycle. The operation of the impulse corrector in this case is as described before, except 30 that repeating relay 219 does not restore immediately upon the quicker reoperation of line relay 203, but remains operated until its locking circuit is opened upon the operation of the impulse-lock relay 221, which operation occurs at the same 35 time that the initial circuit of relay 219 normally is opened.

Correcting long impulses at normal frequency

It will now be assumed for the moment that 40 the line of substation SS2, although equipped with a calling device properly adjusted to operate at the normal speed, has characteristics which cause line relay 203 to delay abnormally long in reoperating after it has restored responsive to 45 an interruption in the line circuit. Under this condition, each of the impulses delivered to repeating relay 219 is longer than normal. The impulse corrector in this case operates as previously described, as the repeating relay 219 50 merely remains operated for a very slight interval over its initial circuit after its locking circuit is opened upon the operation of pulse lock relay 221.

Correcting impulses from a fast calling device

Although calling devices are intended to be adjusted so that they deliver impulses at a rate of ten a second, the operating speeds normally tolerated in practice range from eight impulses 60 a second to twelve impulses a second. For the purpose of explaining more fully the features of the impulse corrector of Fig. 2 it will now be assumed that the calling device at substation SS2 is slightly out of adjustment so that it sends 65 impulses at a rate of twelve a second instead of ten a second. Under this condition, the reoperation of repeating relay 219 occurs sooner pursuant to the second impulse than when the impulses are received at the rate of ten a second. Under this 70 condition, the pulse timer relay 225 has not operated when relay 219 reoperates at the beginning of the second impulse received from the calling line. Nevertheless the pulse locking relay 221 is released when its locking circuit is opened upon 75

the reoperation of relay 219, and the correspondingly shorter repeated impulse is terminated when relay 221 restores.

5 *Correcting impulses from a slow calling device*

In order to explain the operation of the impulse corrector still further, it will now be assumed that the calling device on the calling line is slightly out of adjustment in such a way as to cause the calling device to generate impulses at the minimum allowable frequency (usually at about eight impulses a second). Under this condition, repeating relay 219 is not reoperated pursuant to the second impulse by the time the pulse-timer relay 225 operates following the closure of its circuit by the pulse-lock relay 221, under the control of the pulse-timer relay 223. The termination of the first repeated impulse therefore is effected (six-tenths of a normal impulse cycle after it began) under the control of relay 225, as relay 225 opens the locking circuit of the pulse-lock relay 221 and restores relay 221, in spite of the fact that relay 219 has not yet operated.

In summation of the operations of the impulse corrector just described, it may be pointed out that the pulse-timer relay 225 is adjusted so as to permit the repeated impulses to be of maximum length when the calling device is operating more slowly than normal, while the termination 30 of the repeated impulse is brought about by the reoperation of the repeating relay pursuant to the next received impulse when the calling device is operating at the maximum allowable speed, it being kept in mind that the starting of 35 the repeated impulse is delayed for a predetermined time (usually four-tenths of a normal impulse cycle) after the repeating relay has operated responsive to the incoming impulse. It is to be understood, however, that the timing described for the corrector is given by way of example only.

As is apparent the dial-out relay 216 responds to each repeated impulse and applies 60-cycle current to the conductors of the trunk line TL2 each time it responds, for the purpose of controlling the switching operation in the distant exchange C in a manner to be subsequently made clear. The resistor connected in circuit adjacent relay 215 is introduced for the purpose of 50 improving the operation of the dial-out relay.

It may be pointed out that the condensers 256 and 257 operate in conjunction with the retard coil 215 to act as a filter to suppress undesirable harmonic frequencies, commonly present in commercial 60-cycle current.

When the series of impulses is terminated, repeating relay 219 does not reoperate, and the final repeated impulse is terminated upon the previously described operation of the pulse-timer relay 225. At the end of the series of impulses, the outgoing series relay 218 restores, permitting the shunt-control relay 213 to become reoperated from the grounded release trunk conductor 262 over its previously traced circuit, including conductor 264. The preparing relay 214 restores when its circuit over conductor 266 is opened at the inner upper armature of the outgoing series relay 218.

The previously described operations are repeated for each subsequent series of impulses corresponding to a digit in the desired number.

Answering supervision

When the number has been completely dialled, 75 and while the calling subscriber is awaiting a

response, relays 203, 204, 205, 213, and 217 are in operated position because of operations described heretofore, while the remaining relays of the impulse repeater IR3 are in normal condition. With the repeater in this condition, an impulse of 60-cycle current is received over the trunk line TL2 from the called exchange when the called subscriber responds. This impulse of current is sent back from the impulse repeater IR4, Fig. 1, in exchange C, in a manner which will be subsequently explained in connection with a call in the reverse direction over the trunk line TL2.

When the answering-supervision impulse is received over the trunk line TL2 from the distant exchange, the impulse receiving relay 226 responds. This relay is shunted around the talking condenser associated with the right-hand repeating coil windings, in series with condenser 272. The relay 226 is an alternating-current relay having a partially split core with one section shaded or retarded, as indicated in the drawings. Accordingly, the relay does not vibrate in unison with the alternating current, but it operates and remains operated throughout an entire impulse of several cycles.

Upon operating at this time, impulse receiving relay 226 closes a circuit through contacts of the selector-seizing relay 208 and the inner upper armature of the operated cut-through relay 205 for answering-supervisory relay 202. Relay 202 is a "two-step" relay, so designed and adjusted that an energization of its upper winding alone results in its operation through its first step only, in which condition only its locking contact is operated. This locking contact is identified by the letter "X" in the drawings, as is also the case with the various other two-step relays shown throughout Figs. 2, 3, and 4.

Upon operating through its first step only, the two-step answering-supervisory relay 202 closes a locking circuit for itself at its inner lower armature (the locking contact) through the lower armature of relay 201 to the grounded release-trunk conductor 262. No current flows through the lower winding of relay 202 for the time being, because the initial circuit of the upper winding of the relay is still established at the contacts of the impulse receiving relay 226.

When the answering supervisory pulse is terminated, impulse receiving relay 226 restores and opens the initial circuit of the upper winding of relay 202, whereupon the relay becomes fully energized through the two windings in series and operates completely. At its lower armature, relay 202 prepares a locking circuit for the disconnect-supervisory relay 201 at its upper armature it transfers the supervisory-control circuit from its own upper winding to the winding of the disconnect-supervisory relay 201 and at its inner upper and middle upper armatures it reverses the connections between the windings of line relay 203 and the incoming talking conductors 261 and 263, thereby bringing about a reversal of current-flow in the conductors of the calling line. This reversal of current-flow is used for the purpose of giving answering supervision in case the calling line is a line extending from an operator's switchboard, and it is used to operate a meter or call register either in the exchange or on the subscriber's premises in case the calling line is a measured service line.

The circuits of the impulse repeater IR3 remain in the present condition throughout conversation. 75

Disconnect supervision

When the conversation has been terminated, the two subscribers replace their receivers. Assuming that the receiver is first replaced at the 5 distant substation, a disconnect-supervisory signal is received over the trunk line TL2 from the distant exchange being transmitted therefrom in a manner to be brought out hereinafter. When this disconnect supervisory signal is received being an impulse of 60-cycle alternating current), 10 impulse-receiving relay 226 responds and operates the disconnect supervisory relay 201 through its first step, the circuit including the upper armature of the operated answering-supervisory relay 202. Upon operating through its upper winding, the disconnect-supervisory relay 201 is magnetized only to an extent that permits the 15 operation of its lightly adjusted locking armature (the inner lower armature). The operation of 20 the inner lower armature of relay 201 results in the closure of the locking circuit from grounded release conductor 262 through the lower armature of the operating answering-supervisory relay 202.

25 When the impulse receiving relay 226 now restores, the locking circuit becomes effective and the two windings of relay 201 are energized in series, strengthening the magnetic field sufficiently to bring about a complete operation of the relay. Upon completely operating, relay 201 opens the circuit of answering-supervisory relay 202 at 30 its lower armature, whereupon supervisory relay 202 releases and restores the current flow in the calling line to its normal direction by reversing the connections between line relay 203 and incoming talking conductors 261 and 263 to normal. This operation is used to give disconnect supervision in case the call is from an operator's 35 switchboard and it may also be of utility in many other situations, as is well known.

Releasing the established connection

When the receiver is replaced at the calling 45 substation SS2, line relay 203 is permitted to fall back, whereupon an impulse is transmitted over the trunk line TL2 in the manner described hereinbefore and under the control of repeating relay 219 and relays 221, 223, and 225. At this time, 50 however, repeating relay 219 is not immediately restored, as in a case when a dialled impulse is being transmitted, as the line relay 203 does not reoperate after the receiver has been replaced. Therefore, relay 219 remains operated and maintains the pulse timer relay 223 operated to hold 55 the dial-out relay 216 in operated position to transmit a prolonged releasing impulse over the trunk line. It will be kept in mind, of course, that the outgoing series relay 218 is operated at this time and is maintaining the preparing relay 60 operated at its inner upper armature.

At the end of the interval for which it is 65 adjusted, release relay 204 restores, as its circuit is not again closed by line relay 203. Upon restoring, relay 204 removes ground potential at one point from release-trunk conductor 262, but conductor 262 is maintained grounded for the time being at the upper armature of the outgoing series relay 218. At its inner upper armature, 70 release relay 204 also opens the circuit of cut-through relay 205, permitting slow-acting cut-through relay 205 to restore after a slight interval. Upon restoring, cut-through relay 205 opens the circuit of the outgoing series relay 218 at its 75 inner lower armature and opens the locking cir-

cuit of the pulse timer relay 217 at its lower armature. As a result, relays 217 and 218 restore. Relay 218 opens the circuit of the preparing relay 214 at its inner upper armature, and at its lower armature it disconnects the repeating relay 219, whereupon repeating relay 219 restores and permits impulse timer relay 223 to restore and open the circuit of the dial-out relay 215. Relays 214 and 216 are therefore restored to terminate the prolonged release impulse being 10 transmitted to the distant end of the trunk line TL2.

At its upper armature, outgoing series relay 218 finally removes ground potential from the release trunk conductor 262 so as to permit the 15 lineswitch LS2 and the selector LS3 to release and clear out and to free the repeater IR3 for further use.

The release of the connection set up through the repeater IR4, Fig. 1, in the distant exchange 20 B takes place responsive to the release impulse in a manner which will become clear upon a further perusal of the specification.

Call from exchange C to exchange B

25

In order to explain the remaining portions of the impulse repeater IR3, Fig. 2, and to explain the way in which this impulse repeater operates in connection with a call in the reverse direction, it will now be assumed that the subscriber 30 at substation SS4, Fig. 1, desires to obtain connection with a subscriber, at substation SS2, for example, in exchange B. Assume that the line switch LS4, Fig. 1, seizes the selector S6 when 35 the receiver is removed at substation SS4, and that the selector S6 seizes the trunk line TL2 by way of the impulse repeater IR4 when the digit 0 is dialled. Under this condition, the repeater IR4 operates as previously described for 40 the impulse repeater IR3, Fig. 2, to transmit a seizing impulse over the trunk line TL2.

Seizing the incoming selector

At this time, this impulse is received at the 45 repeater IT3, Figs. 1 and 2, from the impulse repeater IR4, Fig. 1. Impulsing receiving relay 226, Fig. 2, responds to the receiving impulse and closes a circuit through contacts of relays 208 and 205 for the lower winding of the two-step selector-seizing relay 208. Responsive to the closure 50 of the circuit through its lower winding, relay 208 is energized only sufficiently to operate its lightly adjusted inner upper armature to close the locking circuit.

55 It is to be noted that incoming-release relay 207 is normally connected in parallel with the lower winding of relay 208, by way of armature 245. Incoming-release relay 207, having a slow-operating characteristic, is not operated 60 at this time, as the seizing impulse is short, relative to the releasing impulse.

When the seizing impulse is terminated and the impulse receiving relay 226 restores, the locking circuit for relay 208 becomes effective and 65 current flows through the two windings of the relay in series. As a result, relay 208 now operates fully. Upon operating fully, relay 208 grounds the release trunk conductor 262 at its upper armature by way of the upper armature of 70 busy relay 206, thereby guarding the trunk line TL2 and the repeater IR3 against seizure in exchange B, and bringing about the operation of shunt-control relay 213. At armature 241 and its middle lower armature, relay 208 connects 75

the talking conductors extending to the left from the left-hand repeating coil windings to the talking conductors 281 and 282 extending to the incoming selector S5, Fig. 1, while at its lower 5 armature it completes a control across the talking conductors 281 and 282 from the upper talking conductor through the upper left-hand repeating coil winding, conductor 273, contacts of relays 223 and 221 of the impulse corrector, 10 lower armature of relay 208, resistance element 271, upper winding of the electro-polarized supervision-control relay 212, and through the lower left-hand repeating coil winding to the lower talking conductor.

15 The line relay (not shown) of selector S5 is operated over the bridge circuit above traced to prepare the selector for its usual operation, but the electro-polarized supervision control relay 212 is not operated at this time, as it is designed 20 and adjusted so as to operate only in case the current is flowing through both windings in the same direction.

25 As a further result of its complete operation, selector seizing relay 208 places a ground potential on conductor 275 at its inner lower armature thereby preparing a locking circuit for relays 209, 210, and 211 and closing a circuit through resistance element 274 for the polarizing winding of the electro-polarized relay 212. It disconnects the junction of its own winding from incoming-release relay 207 at armature 245; at armature 244 it connects up the common timing impulse conductor 276 for a purpose to be explained subsequently; and at armature 242 it transfers the control lead coming from the contacts of the impulse receiving relay 226 from the junction of its own upper winding to the two-way repeating relay 219, preparatory to operating relay 219 and the associated impulse corrector to transmit impulses to the seized selector S5, connected to the conductors 281 and 282.

Repeating the incoming dial impulses

When the calling subscriber at substation SS4, Fig. 1, manipulates his calling device or dial, in accordance with the first digit in the number locally assigned in exchange B to the line of substation SS2, a series of alternating current impulses is transmitted in the manner hereinbefore described from the impulse repeater IT4, Fig. 1, in exchange B over the toll line TL2 incoming to the impulse repeater IR3, Figs. 1 and 2. The impulse receiving relay 226 is operated momentarily responsive to each of the received impulses of the series. Each time it operates, impulse receiving relay 226 closes a circuit through the operated armature 242 of relay 208 for the repeating relay 219. Each time it operates, relay 219 closes a circuit for the incoming series relay 220, as the outgoing series relay 218 is not operated at this time. By the combined action of repeating relay 219 and the pulse timer relay 225 incoming series relay 220 is operated and maintained operated throughout each incoming series of impulses. Upon operating, incoming series relay 220 disconnects the lower armatures of pulse lock relay 221 and pulse timer relay 223 from conductor 268 leading to the dial-out relay 216, and it prepares a circuit for operating the incoming release relay 207, which circuit is effective to operate the relay only when the established connection is to be released responsive to a prolonged releasing impulse.

75 Relays 219, 221, 223, and 225 cooperate in the

manner hereinbefore explained to secure the repeating of corrected impulses. The impulse repeating is performed by pulse timer relay 223 in conjunction with pulse lock relay 221, as in the described example of a call from exchange A to exchange B. In the present example, the impulses delivered constitute breaks in the loop circuit extending to the seized selector S5, and are delivered at the upper contacts of relays 221 and 223 instead of at the lower contacts of these relays. As before, each impulse is repeated upon the operation of relay 223 and is terminated either by relay 221 or by relay 223, whichever one restores last.

When incoming series relay 220 operates, it 15 breaks the established circuit of the shunt control relay 213 at its upper armature, permitting relay 213 to restore and shunt the upper left-hand winding of the associated repeating coil at its upper armature. At its lower armature, shunt 20 control relay 213 by-passes the lower left-hand winding of the associated repeating coil, the upper winding of supervision control relay 212, and resistance element 271. With relay 213 deenergized, it is to be noted that the control bridge across the 25 talking conductors includes the resting contact and upper armature of relay 213, conductor 273, upper contacts of the impulse-corrector relays 223 and 221, lower armature of selector-seizing relay 208, and the resting contact and lower armature 30 of relay 213. The impusing bridge is shunted by a circuit which includes the lower left-hand repeating coil winding, associated talking condenser, and the resistance element 270, giving a control condition over the line relay (not shown) 35 of the selector S5 which has been found by experiment to be very good.

At the end of the series of impulses, incoming series relay 220 restores and again connects up shunt control relay 213 to permit the latter re- 40 to operate and place the circuits associated with the repeating coil windings in talking condition.

The selector S5 is operated responsive to the first repeated series of impulses, and it selects an 45 idle connector in the desired group, the connector C4, Fig. 1, for example.

Under the assumed condition, the connector C4 is operated in the usual manner responsive to the two series of repeated impulses corresponding to 50 the two final digits in the called number to extend connection to the line of the desired substation SS2.

Answering supervision

55

When the called subscriber responds, the connector C4, Fig. 1, operates in the well known manner to reverse the current flow in its incoming talking conductors. The holding circuit for the line relay (not shown) of the connector C4 60 includes the upper winding of the electro-polarized supervision-control relay 212, Fig. 2. As a result, when the current flow is reversed, the two windings of relay 212 are energized in the same direction, and the operation of the relay is thus 65 secured.

Upon operating, relay 212 places a shunt around the resistor 274 so as to increase the current flow through its lower winding momentarily to maintain the relay operated for the time being irrespective of the direction of current flow in the upper winding. At the same time, relay 212 breaks the circuit of the shunt control relay 213 at its upper armature, momentarily deenergizing the shunt-control relay to shunt out the control wind- 75

ing (the upper winding) of the supervision control relay 212, leaving relay 212 entirely under the control of its lower winding.

At the lower armature, relay 212 begins a series of operations which result in the transmission of an answering-supervisory impulse back to the calling exchange C. This is effected in a manner which will now be described.

With relay 212 operated, ground potential on the grounded conductor 275 is extended at the lower armature of relay 212, through armature 255 and its resting contact, the lower armature of cut-through relay 205, inner upper armature and resting contact of pulse-timer relay 217, and thence by way of conductor 266 to the preparing relay 214. Preparing relay 214 is operated to prepare the circuit for the transmission of an alternating current impulse over the trunk line TL2. At its lower armature, relay 214 closes a circuit over conductor 267, through contacts of relay 217, and thence by way of conductor 268 to the dial-out relay 216. Relay 216 is operated to start the alternating-current impulse, and at its lower armature it closes a branch circuit over conductor 269 and contacts of the outgoing-series relay 218 for the pulse timer relay 217.

After the interval for which it is adjusted, relay 217 operates and closes a locking circuit for itself at its inner upper armature, at the same time breaking the energizing circuit of relay 214. It also disconnects relay 216 at its lower armature, with the result that relays 214 and 216 restore to terminate the answering supervisory impulse.

As a further result of its operation, relay 217 closes a circuit at its upper armature which extends ground potential from the serially related lower armatures of the line and release relays 203 and 204, by way of conductor 265 and the inner lower armature and resting contact of the disconnect-supervisory relay 211, to operate the answering-supervisory relay 210.

When relay 210 operates, it locks itself at its inner lower armature to the grounded conductor 275; it opens the shunt circuit around the resistance element 214 at armature 251; it reoperates shunt-control relay 213 at its upper armature to place the circuit in talking condition; it prepares a locking circuit at armature 252 for the disconnect supervisory relay 211; and at armature 255 it opens the locking circuit of pulse timer relay 217, permitting relay 217 to restore. Relay 214 does not reoperate now because its circuit is open at armature 255.

As a result of the described operations the answering supervisory impulse has been transmitted back over the trunk line TL2 to the calling exchange to bring about in the repeater, Fig. 1, operations described previously in connection with the repeater IR2, Figs. 1 and 2, in the case of a call in the opposite direction over the trunk line TL2.

It is to be noted that relay 212 is temporarily rendered non-responsive in the manner described, while the answering supervisory impulse is retransmitted back over the trunk line. This is for the purpose of rendering the operation more reliable and to insure the completion of the signal in the event that the switchhook is not permitted to operate in normal manner upon its removal and to insure correct signal transmission in the event that the switchbook is subsequently moved up and down rapidly.

The circuits in the repeater IR3 remain in this condition during conversation, relays 208, 210, 75 212, and 213 being held operated.

Disconnect supervision

Assume now that the conversation has been terminated and that the called subscriber at substation SS2, Fig. 1, is the first to replace his receiver. When the receiver is replaced, the connector C4, Fig. 1, operates in the usual manner to reverse the current flow in its incoming talking conductors back to normal direction, whereupon the current flow in the control winding of electro-polarized supervision-control relay 212, Fig. 2, is again reversed so that the two windings again oppose one another. Under this condition, relay 212 restores. Upon restoring, relay 212 closes a circuit at its lower armature from the grounded conductor 275 and through the lower armature of the answering-supervisory relay 210 for the winding of disconnect supervisory relay 211. Upon operating, relay 211 closes a locking circuit for itself at its middle lower armature to conductor 275, by way of the operated armature 252 of relay 210, whereby it is maintained operated for the time being independent of further action of supervision-control relay 212.

At its lower armature, relay 211 extends ground potential from its own locked winding to the winding of the preparing relay 214. Relay 214 is again operated to prepare for transmitting an alternating-current disconnect-supervisory impulse over the trunk line TL2. At its lower armature it again closes the circuit over conductors 267 and 268, through contacts of pulse-timer relay 217 for dial-out relay 215. Relay 215 now operates and transmits the supervisory impulse over the trunk line TL2, at the same time closing a circuit over conductor 269 for pulse-timer relay 217.

When relay 217 operates, after the period for which it is adjusted, and breaks its initial circuit it does not lock itself because its locking circuit is open at armature 255 of relay 210 and at the lower armature of relay 212. Relay 217, being slow-releasing (as well as slow-operating), remains operated for a slight interval. At its upper armature relay 217 applies ground potential, obtained through the lower armatures of line and release relays 203 and 204, by way of conductor 265 and the inner lower armatures of the operated relay 217 to the junction of the winding of relay 210 and the associated current-supply resistor. Relay 210 is thereupon shunted and caused to restore. Upon restoring, relay 210 disconnects its own winding at its inner lower armature from conductor 275, and at armature 252 it opens the locking circuit of relay 211, in addition to opening the initial circuit of relay 211 at its lower armature. As a result, relays 211 and 214 now restore also. Slow acting relay 217 now finally restores.

At this point it may be mentioned that the supervision control relay 212 is again operated to bring about the results hereinbefore described in case the receiver is again removed or the hookswitch again raised at the called substation before the connection is released, as in the case of "flashing" the switchhook to signal the operator when the call has been extended through an operator's switchboard. It will be observed, therefore, that the operation of transmitting answering and disconnect supervisory signals may be repeated over and over as many times as relay 212 is operated and released.

Releasing the established connection

When the subscriber at the calling substation SS4 replaces his receiver to release the established

connection, the repeater IR4, Fig. 1, in exchange C is caused to go through the operations described in connection with repeater IT3, Figs. 1 and 2, to secure the release of the lineswitch LS4 and the selector S5, and to transmit a prolonged releasing impulse over the trunk line TL2 from exchange C to exchange B, Fig. 1. When this prolonged impulse is received, impulse receiving relay 226 remains operated for a much greater interval than when it is responding to setting impulses. When it responds at this time, it operates the two-way repeating relay 219 (through armature 224 of selector seizing relay 208 as before described), and relay 219 brings about the successive operation of relays 223, 221, and 225. Relay 225 closes a circuit for relay 207 at its lower armature through the lower armatures of the operated relays 221 and 220, relay 220 being operated at the upper armature of relay 219. Relay 207 because of the relatively great length of the releasing impulse has its circuit closed for a sufficient interval to bring about its operation. Relay 207 it will be noted is slow to operate because of its construction and does not therefore operate during the repeating of switch setting impulses because of its slow operating characteristic. Upon operating relay 207 extends its operating ground potential to the locking circuit of relay 298 and disconnects the locking circuit of relay 208 from the local supply of ground potential.

When the release impulse has been terminated, relay 226 restores and permits relays 219, 223, 221, and 225 to restore successively, and the incoming series relay 220 to restore after a short interval. The restoration of relay 225 results in the opening of the circuit of the incoming release relay 207. Since relay 207 is operated when its circuit is opened, the locking circuit of the selector-seizing relay 208 is also opened and also 208 restores immediately. Relay 207, being somewhat slow in restoring as well as slow in operating, does not restore until a short time later.

Upon restoring, relay 208 removes ground potential from release-trunk conductor 262 at its upper armature so as to make the repeater IT3 and the trunk line TL2 test idle again to selectors such as S3, and at armature 241 and 242 it disconnects the conductors 281 and 282 leading to the incoming selector S5, thereby bringing about the release of the connection set up by way of the selector S5. All of the circuit apparatus of the impulse repeater IR3 is in normal condition.

Forced release at the repeater IR3

Special arrangements have been provided, including the two-step forced-release relay 209 to force the repeater IR3 to clear out under certain conditions without receiving a releasing impulse over the trunk line IT2 from the distant exchange.

This arrangement is of utility in case the distant repeater IR4, Fig. 1, develops a fault and does not properly transmit the releasing impulse, and it is of utility in case the impulse receiving relay 266 is spuriously operated, as for example, responsive to an electrical discharge which may, for instance, occur during an electrical storm. At any rate, when the selector-seizing relay 208 is operated responsive to a seizing impulse received at the impulse receiving relay 226 and causes the associated selector S5 to be seized and prepared for operation, the common timer lead 276 coming from the common impulse device 283 is connected at armature 244 through contacts of relays 210 and 209 to the upper winding of the two-step forced-

release relay 209. The common impulse device 283 may be arranged to transmit an impulse over conductor 276 once during an interval of, for example, thirty seconds to a minute. This is for the purpose of allowing from thirty seconds to a minute for a call to be put through to the desired line and to be answered, as will appear from the description to be given.

The first impulse received over conductor 276 following the operation of armature 244 results in the partial energization of relay 209 through its upper winding. Only the lightly adjusted locking armature of relay 209 is operated at this time, and it closes a locking circuit for the two windings in series from the grounded conductor 15 275 by way of armature 252 and its resting contact.

When the impulse is terminated, relay 209 operates fully on account of its two windings being at that time energized in series. 20

With relay 209 operated fully, the receipt of the next impulse (say thirty seconds to one minute later) results in the closure of a circuit through the operated upper armature of relay 209 for the incoming release relay 207 unless the answering 25 supervisory relay 210 has been operated in the meantime to restore relay 209. If relay 209 is still operated, relay 207 responds to the impulse and opens the initial locking circuit of relay 208, holding this relay operated in parallel with its 30 own winding for the time being. Then, when the impulse is terminated, relay 208 restores and clears out the repeater as described. In the normal operation of the repeater, the call is put through to the desired line and is ordinarily answered, or else the connection is released in the normal way if the called line is busy, before the forced released described has had time to be effective. 35

It is to be noted that the answering supervisory relay, which is operated as previously described when the called subscriber responds, opens the locking circuit of relay 209 at armature 252 so as to restore relay 209 and thereby prevent the forced release operation from being performed during conversation. It will be understood, however, that the forced release operation may be again initiated in case the regular releasing operation does not take place following the restoration of answering supervisory relay 50 210, as described, when the receiver is replaced at the called substation. This will be readily apparent, as relay 210, upon releasing, again prepares the locking circuit of relay 209 and again connects the relay to the common impulse lead 55 276.

Double seizure of an inter-exchange trunk line

In order to explain an additional special provision it will be assumed that the trunk line TL2, 60 Figs. 1 and 2, is seized at about the same moment in exchanges C and B. When the repeater IR3 is seized in exchange B, the placing of ground potential on the release trunk conductor 262 by the seizing switch brings about the hereinbefore 65 described operation of shunt control relay 213 over conductor 264, accompanied by the described successive operation of the line, release, and cut-through relays 203, 204, and 205. The operation of the cut-through relay 205, as hereinbefore described, at its lower armature sets in motion the operation involving relays 214, 215, and 217 to cause a seizing impulse to be transmitted to the distant exchange. 70

It will be understood that similar operations 75

are taking place at the same time in the distant exchange, and the two seizing impulses are transmitted without avail if the trunk line seizure at the two ends is accomplished exactly at the 5 same time, which happening is extremely rare. If one seizure, the seizure in exchange B, for instance, takes place slightly later, the cut-through relay 205 is unable to operate responsive to the operation of release relay 204, as the selector-seizing relay 275 has been operated responsive to the seizing impulse received from the distant end. In this case, busy relay 206 is operated through the actuated armature 243 of seizing relay 208. Upon operating, relay 206 disconnects the incoming release trunk conductor 262 from the upper armature of relay 208, leaving the incoming release trunk conductor 262 grounded only at the upper armature of release relay 204. Busy relay 206 also connects the associated 10 common busy-tone lead through the usual small limiting condenser to the upper talking conductor, thereby transmitting busy-tone current to the calling substation to inform the subscriber thereof of the busy condition.

15 When the calling subscriber replaces his receiver under these conditions, the line and release relays 203 and 204 restore successively, and release relay 204 opens the circuit of the slow releasing busy relay 205. Release relay 204 also disconnects ground potential at its upper armature from the incoming release trunk conductor 262 so as to permit the local switches involved in the connection to release. A moment later busy relay 206 restores and at its upper armature 20 again places ground potential on release trunk conductor 262 through the actuated upper armature of selector-seizing relay 208, thereby guarding the trunk line against further seizure in exchange B.

40 Abandoned calls

Special provisions have been made for clearing out the repeaters on the two ends of a trunk line when a call is abandoned before the connection is put through to the called line. It will be recalled that a releasing impulse is transmitted by the repeater IR3 over the trunk line TL2 when an outgoing connection through the repeater IR3 of the trunk line TL2 is to be released. This impulse is transmitted throughout the time required for the slow releasing release, cut-through, and outgoing-series relays 204, 205, and 218, to restore successively, following the opening of the circuit of release relay 204 by line relay 203. It will be recalled also that the circuit for preparing relay 214 is closed at this time at the inner upper armature of the outgoing series relay 218, operated through contacts of relays 203 and 205, and that the releasing impulse is transmitted 45 through the contacts of dial-out relay 216, which is operated over conductor 258 from the impulse corrector and under the control of repeating relay 219. Repeating relay 219, it will be recalled, is operated through contacts of line relay 203 and 50 outgoing series relay 218 to maintain pulse-timer relay 223 operated to hold the circuit of dial-out relay 216 closed until relay 218 restores.

In the example assumed and described hereinbefore, the releasing operations took place only 55 after the call had been completed and conversation had taken place. It is evident that the releasing impulse will be transmitted from the repeater IR3 over the trunk line TL2 at any stage 60 of the connection after the repeater IR3 has been seized, as the relays 203—205 operate successively

upon the seizure of the repeater and thereby make the necessary circuit preparations for the transmission of the releasing impulse.

A special condition which must be considered is the one arising when the calling subscriber 5 abandons the call only a moment after a selector such as the selector S3 has been operated to extend a connection to the impulse repeater IR3. At this time, the preparing and dial-out relays 214 and 215 are operated to transmit a relatively 10 short seizing impulse over the trunk line TL2, the length of which is determined by the slow-operating characteristic of pulse-timer relay 217.

Now, in the event that the calling subscriber 15 replaces his receiver and brings about the deenergization of line relay 203 while the seizing pulse is being transmitted, outgoing series relay 218 is operated by line relay 203 through contacts of relay 205 to close a new circuit for preparing relay 256 and to connect up repeating relay 219. Repeating relay 219 operates and brings about the operation of pulse-timer relay 223 to close a new circuit over conductor 268 to maintain dial-out relay operated. The circuit for the pulse timer relay 217 is opened at the lower contacts of outgoing series relay 218, whereby the operation of pulse timer relay 217 is prevented at this time.

Relays 214 and 216 are now maintained energized to prolong the impulse of current being transmitted over the trunk line TL2 until relays 30 204, 205, and 218 restore.

When relay 218 restores, relays 214 and 216 are permitted to fall back as hereinbefore described, finally terminating the impulse.

As will be pointed out subsequently, this prolonged impulse, instead of causing the distant repeater IR4, Fig. 1, to seize the associated incoming selector, causes the said repeater IR4 to refrain from seizing the associated incoming selector and to become cleared out upon the termination of the impular.

Consider now the case when the trunk line TL2 is seized in exchange B by way of impulse repeater IR4 and the call is immediately abandoned. Under this condition, as was described above, 45 the impulse received at the impulse repeater IR3 is a prolonged releasing impulse in place of the somewhat shorter seizing impulse ordinarily received as the first impulse pursuant to the establishment of a connection.

Upon the receipt of this impulse, impulse receiving relay 226 responds and closes a circuit through contacts of relay 208, and through the inner upper armature and resting contact of cut-through relay 205, for the lower winding of the two-step 55 selector-seizing relay 208. Relay 208 operates as before to close a lightly adjusted locking contact (the inner upper armature and associated contact). At the same time, a circuit extends in parallel with the lower winding of relay 208 through armature 245 and its resting contact for the incoming-release relay 207. Relay 207 is a slow acting relay, being adjusted so that it does not operate in parallel with the lower winding of relay 208 when a relatively short selector-seizing 60 impulse is being received. In the present assumed example, however, the impulse being received is a prolonged releasing impulse and is of sufficient duration to bring about the operation of relay 207. Upon operating, the relay 207 removes the local ground connection from the inner upper armature of relay 208 and substitutes the ground potential now being applied by the armature of the impulse-receiving relay 226. As a 70 65 75 80 85 90 95 98 99 100

result of this, when relay 226 restores, at the end of the prolonged impulse, there is no locking potential present to cause the upper winding of relay 208 to become energized in series with the lower winding of the relay. Relay 208, therefore, does not operate fully but restores and opens its locking contacts. A moment later, relay 207 restores and leaves the impulse repeater IR3 in a completely cleared-out condition.

10 *Composed-trunk-line operation without voice current repeaters*

The foregoing description of the operation of the repeater IR3, Figs. 1 and 2, has been given 15 under the assumption that the trunk line TL2 does not include a physical circuit composed for telegraphic or similar operation over the conductors thereof. It has been determined by experimentation that a 60-cycle current is rather low 20 in frequency for advantageous signalling over a circuit composed for telegraphic or similar signal operation, as there is likelihood of mutual interference between the dialling impulses and the telegraphic impulses. For operation in conjunction 25 with composed lines, the leads extending down from the contacts of the dial-out relay 216 are connected to a higher frequency source, 120-cycles for example. 120-cycle current is recommended mainly because it may be obtained readily 30 from the commercial 60-cycle current by using a well known form of frequency-doubling device. The impulse receiving arrangement is modified somewhat when 120-cycle signalling current is used.

35 For the reception of 120-cycle signal impulses, the jumpers extending to relay 226 and its armature are removed and jumpers indicated by the dotted lines are connected up to the circuit of relay 228 and to the armature of relay 229. It 40 may be pointed out that the retard coil 227 and the condenser 254, in series, form a tuned couple designed to peak at about 120-cycles, whereby a maximum potential is impressed on the terminals of polarized relay 228, relay 228 being in 45 shunt of condenser 254. The armature of relay 228 normally stands in neutral position and is forced first in one direction and then in the other by the successive positive and negative surges of the 120-cycle current.

50 Each time the armature of relay 228 is moved in either direction, the circuit of relay 229 is closed. Relay 229 is shunted by a relatively high resistor, which arrangement makes the relay sufficiently slow to release that it remains operated 55 throughout a series of vibrations of the armature of polarized relay 228, but relay 220 restores almost instantly when the armature of relay 228 comes to rest.

60 From the above explanation it will be seen that relay 228 responds to each received impulse of 120-cycle current by vibrating its armature, and that relay 220 operates for the duration of the impulse and then restores immediately. As 65 a result, relay 229 operates to control the circuits in the impulse repeater IR3 in the manner described in connection with the armature of impulse receiving relay 226.

70 It may be pointed out that the variable resistor 255, shunted across the polarized relay 228, may be adjusted from time to time in order to improve the response of relay 228 under, for example, varying temperature or other conditions 75 which may affect the operation.

Voice frequency dialling—slow-relay signal control

It has been previously pointed out that the trunk lines passing from exchange A to exchange B, Fig. 1, pass through a voice-current-repeater station, there being a separate two-way voice-current repeater for each trunk line, and that the practical limitations of a voice-current repeater require that the dial impulses be transmitted as impulses of current of a voice frequency 10 and of an intensity of the same order as the intensity of the voice currents. It is necessary, therefore, to make special provisions to prevent impulses of voice currents arising during conversation from being interpreted as signalling impulses, as will be pointed out in the course of the description.

Two modifications of the voice-frequency dialling arrangement have been provided, one being 20 shown in Fig. 3, the other in Fig. 4. The principal difference between Figs. 3 and 4 is that, in Fig. 3, slow-releasing relays have been provided to control signalling operations apart from the actual dialling impulses, while in Fig. 4 a tuned 25 signal-receiving relay is provided to respond to the signal-frequency modulations of the thousand-cycle carrier current.

The repeater IR1, as shown in Fig. 3, will now 30 be described.

Three vacuum tubes are associated with the repeater IR1, a power amplifier 332, a screen-grid voltage amplifier 331, and a detector tube 338. Plate current and biasing potential for the tubes 336, 337, and 338 are furnished by the rectifier tube 335 and associated apparatus. The transformer 331, it will be noted, has one winding for lighting the filament of the rectifier tube 335, another winding for furnishing the current to the rectifier for use by the vacuum tubes, and a 40 third winding for heating the filaments of the heater-type tubes 336, 337, and 338. Choke coils 332 and 333, together with the associated bypass condensers, form the usual type of filter to smooth out the sipples in the rectified current. 45 The multi-tap resistor indicated generally by the reference character 334 provides nine volts positive potential over lead 346 for grid biasing purposes, 100-volt positive plate and screen-grid current over lead 347, one 115-volt current over lead 50 348 and 200-volt current over lead 349.

55 Each of the tubes 336, 337, and 338 is of the usual heater type; each includes the heater element, a cathode element, a control grid, and a plate. The voltage-amplifier tube 337 has in addition a screen grid interposed between the usual control grid and the plate element of the tube.

The transformer 361, common to a group of impulse repeaters, furnishes 1000-cycle current 60 for signalling and dialling purposes. The transformer 364, also common to a group of repeaters, furnishes 60-cycle current which is used, as will be subsequently described, for modulating the 1000-cycle current for the purpose of signalling 65 apart from the transmission of switch-setting impulses.

The relays 321, 322, and 323 are each provided with a resistor in shunt of its winding, the resistance of which is relatively high but low enough 70 to permit a small circulating current to flow following the breaking of the relay circuit. The relay is adjusted to hold up by virtue of this small circulating current between impulses received at the rate of sixty a second, but neither of the re- 75

lays 321, 322, and 323 will remain operated between successive impulses delivered at dial frequency or the frequency ordinarily used to position the automatic switches.

8 Except for the parts described above, the repeater IR1 is quite similar to the repeater IR3.

Call from exchange A to exchange B

10 For the purpose of explaining the operation of the repeater IR1, Fig. 3, will be assumed that the subscriber at substation SS1, Figs. 1 and 3, desires to converse either with a subscriber whose line terminates in exchange B or else one whose line terminates in exchange C. Accordingly, the 15 subscriber at substation SS1 removes his receiver and obtains connection with a first selector, such as S2, by way of the line switch LS1.

When the digit 0, assigned to exchange B, is dialled, the selector S2 raises its wipers opposite 20 the tenth level of bank contacts and rotates them over the contacts in the tenth level in search of an idle trunk line. Assuming that the trunk line comprising conductors 351-353 and extending to the impulse repeater IR1 is the first one found 25 to be idle, this trunk line is seized in the usual manner by the selector S2. At the time of seizure, it may be pointed out, certain of the relays associated with the impulse repeater are in energized condition. Incoming pulse relay 326 is 30 normally energized in the plate circuit of the detector tube 338, and it is normally maintaining the "make" timing relay 321 in energized position. Moreover, the signal repeating relay 309 is normally energized in a local circuit through 35 the associated resistor, and it normally maintains the incoming-release relay 307 in an energized condition.

When the repeater IR3 is seized by the selector S over conductor 351-353, line relay 303 is energized through contacts of the answering supervisory relay 302, conductors 351 and 353, and over the calling line. Upon energizing, line relay 303 brings about the operation of release relay 304, and relay 304 places ground potential at its 40 upper armature on release trunk conductor 352 so as to maintain the switches LS1 and LS2 operated. Relay 304 also operates cut-through relay 305 through armature 375 and its resting contact. Relay 305 at its upper armature and at 45 armature 372 extends the talking circuit through to the repeating coil; it prepares a circuit for the answering-supervisory relay 302 and opens a point in the circuit of selector-seizing relay 308 at its inner lower armature, it prepares a circuit 50 for the outgoing series relay 315 at armature 371, and at its lower armature it places a ground potential on conductor 397, thereby closing a circuit through armature 377 of the pulse-timer relay 316 and its resting contact for the preparing 55 relay 313, so as to start the sequence of operations which will culminate in the transmission of a seizing impulse over the trunk line TL1 to the distant impulse repeater IR2, Fig. 1, by way of the voice-current repeater VCR.

60 *Transmitting the seizing impulse*

When preparing relay 313 operates, it disconnects the conductors of the trunk line TL1 from the right-hand repeating-coil windings at its 65 upper armature and its inner lower armature, and at its lower armature it operates cut-off relay 320 to disconnect "break" timing relay 322 from the back or "break" contact of the incoming-impulse relay 326, and to open a point in the 70 circuit of incoming signal relay 323. Cut-off re-

lay 320 also makes an additional ground connection to the release trunk conductor 352 for a purpose which will become more apparent as the description progresses.

Preparing relay 313 also removes the ground potential, at its middle lower armature, normally applied to conductor 396 by way of the contacts on the outgoing series relay 315, and extends this ground potential to dial-out relay 314 by way of contacts associated with armature 376 of pulse 10 timer relay 316. Dial-out relay 314 operates to connect the out-going conductors of the trunk line TL1 to conductors 393 and 394, leading to the secondary winding of the outgoing transformer 363, preparatory to the transmission of a seizing 15 impulse over the conductors of the trunk line TL1.

The normally energized transfer relay 325 restores responsive to the opening of its circuit previously closed over conductor 396, at the middle 20 lower armature of the preparing relay 313; it disconnects the plate element of the power amplifier tube 336 from the grid circuit of the voltage amplifier tube 337 and the normal direct-current connection through plate resistor 343, and transfers it by way of the primary winding of the outgoing transformer 363 and the armature and resting contact of relay 334 to the secondary winding of the modulating transformer 364. As a result, the plate element of the power-amplifier 30 tube 336 is now supplied with 60-cycle alternating current by way of the primary winding of the outgoing transformer 363. At the same time, the grid circuit of the power amplifier tube 336 is transferred from the tuned secondary winding 35 of the incoming transformer 362 to the secondary winding of the 1000-cycle carrier-current transformer 361. 1000-cycle carrier current is therefore continuously impressed on the grid element of the power-amplifier tube for the time being, 40 while such plate current as flows is driven by a 60-cycle source of alternation potential (the secondary winding of transformer 364).

During each positive half cycle at transformer 364, current flows from ground through the secondary winding of transformer 364 to the plate of the amplifier tube 336 by way of the primary winding of transformer 363 and contacts of the deenergized relay 325. This plate current has the 1000-cycle carrier current impressed on it by 50 the well known action of the grid element.

During each negative half cycle, no current flows in the plate circuit of the power amplifier tube 336. The net result of this is that successive series of 1000-cycle impulses are sent out 55 through the secondary winding of the outgoing transformer 363 and over the trunk line TL1, at the rate of sixty series of impulses a second. Stated in another way, 1000-cycle carrier current is transmitted over the trunk line TL1, modulated 60 by being interrupted sixty times a second.

The 60-cycle modulated 1000-cycle current transmitted over the trunk line TL1 at this time is a seizing impulse, employed in the distant exchange to prepare the repeater IR2, Fig. 1, for 65 incoming operation, as will be later explained.

The seizing impulse now being transmitted is terminated under the control of the pulse-timer relay 316, which is energized in parallel with the winding of dial-out relay 314 through the middle 70 lower armature of relay 314 and contacts of relays 315 and 316. Relay 316 responds to the closure of this circuit after the short time interval for which it is adjusted has elapsed, and locks itself to the grounded conductor 397 at its inner 75

right-hand winding, at the same time opening its initial energizing circuit. At its outer armature, relay 316 closes a circuit through the resistor 379 and over conductor 395 for relay 324; 5 at armature 316, it opens the circuit of dial-out relay 314 and transfers the relay 314 to the control of the energized line relay 303; and at armature 317, it opens the circuit of the preparing relay 313. 10 Relays 313 and 314 now restore and thus terminate the seizing impulse transmitted over the trunk line TL1, and the transfer relay 325 immediately reoperates over conductor 396 when ground potential is reapplied to conductor 396 at 15 the middle lower armature of preparing relay 313.

With dial-out relay 314 restored, transfer relay 314 is operated over conductor 395 and through the resistor 379 by way of the outer contacts of the pulse-timer relay 316. Upon operating, relay 324 prepares a 100-volt plate-supply circuit for power amplifier tube 336 by way of the primary winding of the outgoing transformers 363 and 347, preparatory to transmitting the repeated dial impulses over the trunk line TL1 to the distant exchange. 20

Transfer relay 325 reoperates over conductor 396 and brings the associated circuits again into the position shown in the drawings.

30 *Transmitting the dial impulses to the distant exchange*

As a result of the operations taking place responsive to the seizure of impulse repeater LR1, the preparing impulse has been transmitted over the trunk line TL1 as described, and the pulse-timer relay 316 has operated and locked in operated position. The other relays now in energized condition in the impulse repeater IR1 are the line and release relays 303 and 304, cut-through relay 305, signal-repeating relay 309, incoming-impulse relay 326, "make" timing relay 321, and transfer relays 324 and 325. 35

When the calling subscriber dials the next digit, line relay 303 is momentarily deenergized 40 a number of times depending upon the value of the digit. Each time it deenergizes, line relay 303 closes a circuit at its inner armature and through armature 371 of the energized cut-through relay 305 for the slow-acting outgoing-series relay 315. Relay 315 therefore energizes responsive to the first impulse and remains energized throughout the series of impulses. At its outer right-hand armature relay 315 disconnects ground potential from conductor 396 to again 45 deenergize transfer relay 325, and it reoperates preparing relay 313 to open the talking circuit and to again energize cut-off relay 320. 50

With transfer relay 324 now energized over conductor 395 and through resistor 379, as pointed out, and transfer relay 325 deenergized by relay 315, a 1000-cycle potential is continuously impressed on the grid element of power amplifier tube 336 from the secondary winding of the common 1000-cycle transformer, and the plate element is connected through the upper armature of the deenergized relay 325, through the primary winding of the outgoing transformer 363, and through the armature of the energized transfer relay 324 to the 100 volt plate supply lead 347. The current flowing through the plate circuit of the power amplifier tube from lead 347 is therefore modulated with the 1000-cycle carrier current, and a 1000-cycle carrier voltage is therefore generated in the secondary winding of the outgoing transformer and passes over leads 75

392 and 394 to the contacts associated with the armatures of the dial-out relay 314. 5

The foregoing preparatory actions take place almost instantaneously upon the first deenergization of the line relay 303.

Each time line relay 303 deenergizes, it closes a circuit from conductor 397 (grounded at the lower armature of cut-through relay 305) and through the operated armature 316 of the pulse-timer relay 316 for dial-out relay 314. Relay 314 10 is therefore energized momentarily each time line relay 303 deenergizes. Each time dial-out relay 314 energizes under this condition it connects conductors 393 and 394 (across which a 1000-cycle potential is impressed, as before described) 15 to the outgoing conductors of the trunk line TL1. The net result of this is that an impulse of 1000-cycle current is transmitted over the trunk line TL1 for each momentary deenergization of line relay 303. At its lower armature relay 314 applies ground potential to conductor 395 to shunt transfer relay 324, but relay 324 is adjusted to remain operated nevertheless through a series of dial impulses, by virtue of the well-known slow action of a shunted relay. 20 25

At the end of the series of impulses, line relay 303 remains in an energized condition and the outgoing series relay 315 is permitted to restore. Upon restoring, relay 315 opens the circuit of preparing relay 313 at its right-hand armature 30 whereupon relay 313 restores and permits cut-off relay 320 to restore. Relay 313 also reestablishes the circuit over conductor 397 for transfer relay 325 to again reoperate the said transfer relay. 35

Responsive to the dialling of each of the subsequent digits of the desired number, the foregoing operations are repeated, varying only as to the number of impulses in the series. 40

Answering supervision

After the complete number has been dialled, the circuits in the repeater IR1 remain at rest until the called subscriber responds. At this time, and in a manner which will be pointed out subsequently, an answering supervisory impulse 45 is transmitted back over the trunk line TL1 from the distant exchange to indicate that the called subscriber has entered. This impulse of current is of the nature of the impulse of current transmitted over the trunk line TL1 from the repeater 50 IR1 as a seizing impulse; that is, it is an impulse of 1000-cycle current modulated by a 60-cycle current so that the carrier current is interrupted sixty times a second. 55

It is to be noted that the incoming transformer 362 is connected across branch conductors 391 and 392 so that the incoming supervisory impulse is received at the primary winding of the incoming transformer 362. It is to be noted further that blocking condensers are connected 60 in circuit, one or either side of the primary winding of the transformer 362. The primary winding of the transformer, together with the locking condensers, constitutes a resonant circuit, tuned to peak at about 1000 cycles. An additional resonant circuit bridged across the conductors 291 and 392 includes the coil 365. This additional circuit also resonates in the neighborhood of 1000 cycles. This additional circuit has been found to improve the circuit performance. 65 70

The secondary winding of the transformer 362 is tuned rather sharply to 1000 cycles by the variable shunt condenser shown in the drawings. The incoming 1000-cycle current is transmitted from the secondary winding of transformer 362 75

and through contacts of the operated transfer relay 325 to the grid element of the power amplifier 336. The plate element of the power amplifier 336 is now connected through contacts of the operated transfer relay 225 to the 200-volt plate-supply lead 349 by way of the common resistor 345 and the individual plate resistor 343. Consequently, the 1000-cycle signal impressed on the control grid of amplifier tube 336 is amplified and transmitted to the voltage amplifier 337. The signal is greatly amplified by the voltage amplifier tube 337, so that a high voltage is built up on the plate of the tube, which derives its plate current from lead 349 through the common resistor 345 and the plate resistor 344. This amplified signal voltage is delivered by way of the small-capacity grid condenser 362 to the grid of the detector tube 338. The grid element of the detector tube is connected to ground through the grid-leak resistor 341, the resistance of which is particularly high to cause tube 338 to act as a detector of the grid-leak, grid-condenser type. As a result, the receipt of each impulse of the amplified 1000-cycle signal results in a cessation of the flow of plate current in the detector tube 338 and the incoming-impulse relay 326 accordingly restores. Since the impulses now being received are composed of successive trains of 1000-cycle impulses, at the rate of sixty such trains of impulses a second, or, stated differently, is a 1000-cycle carrier current modulated at sixty times a second, incoming-impulse relay 326 is restored and reoperates sixty times a second. It is restored each time a train of 1000-cycle impulses reaches the grid element of tube 338 and renders the grid strongly negative by the well-known action. Relay 326 is again operated when the train of 1000-cycle impulses subsides and the negative charge of the grid element has been dispelled through the action of the grid-leak resistor 341.

When incoming impulse relay 326 restores the first time, it closes a circuit through contacts of cut-off relay 320 and through the inner armature of the operated relay 321 for the "break" timing relay 322. Relay 322 therefore operates and connects the incoming signal relay 323 in multiple with "make" timing relay 321, through the lower contacts of cut-off relay 320. Due to its slow releasing characteristics hereinbefore mentioned, relay 321 is able to remain energized during the relatively short interruption produced in its circuit by the falling back of impulse relay 326 when it is operating at 60-cycles a second. Each time relay 326 reoperates its recharges or reenergizes relay 321, and, the first time it reoperates, it operates relay 323 in parallel with relay 321. Relays 321, 322, and 323 are maintained operated throughout the series of received 60-cycle impulses, comprising the modulating compound of the 1000-cycle signal impulse.

At the end of the received answering-supervisory impulse, incoming-impulse relay 326 remains operated continuously; "make" timing relay 321 remains operated, and relays 322 and 323 restore.

When the "break" timing relay 322 responds, it opens the repeating-coil-condenser bridge across the incoming talking conductors of the trunk line 70 TL1 so as to minimize the shunting effect of the talking circuit on the remaining portion of the impulse.

When the incoming-signal relay 323 operates, it shunts the signal-repeating relay 309 and 75 causes it to restore. When it restores, relay 309

opens the circuit of the energized incoming release relay 307 and closes a circuit, through the inner lower armature of the operated cut-through relay 305 and the upper armature of relay 302, for the upper winding of the two-step answering-supervisory relay 302. The duration of the impulse is not sufficient to bring about the restoration of incoming-release relay 307.

Responsive to the closure of this circuit, relay 302 energizes sufficiently to operate the lightly adjusted locking armature. At this locking armature a locking circuit for the two windings of the relay in series is closed, by way of the lower armature of disconnect-supervisory relay 301 and the grounded release conductor 352. Incoming 10 repeating relay 311, connected to the resting contact of the armature of incoming impulse relay 326, through contacts of relay 317, may or may not respond to the 60-cycle operation of relay 326, depending upon the adjustment of relay 311. Whether relay 311 so responds or not is immaterial.

When incoming-signal relay 323 restores at the end of the answering-supervisory impulse, and permits the signal-repeating relay 309 to re-operate and open the initial circuit of answering supervisory relay 302 and reestablish the holding circuit of incoming release relay 307, answering-supervisory relay 302 is operated fully to reverse the connections between the incoming talking conductors 351 and 352 and line relay 303. Relay 302 also transfers its operating circuit, at its upper armature, to relay 301, while at armature 359 it prepares a locking circuit for the disconnect-supervisory relay 301.

Current-flow has now been reversed in the calling line for whatever useful purpose it may serve, and the conversation between the two subscribers may proceed as desired.

The repeater IR1 during conversation

Conversation may now take place between the two subscribers. During conversation, relay 325 being operated, the vacuum tubes 336, 337, and 338 are connected in tandem relationship to repeat signals received over trunk line TL1 to the incoming impulse relay 326. As hereinbefore mentioned, only current of 1000-cycles is permitted to pass through to the input circuit of amplifier 336. Nevertheless, it may happen often during conversation that 1000-cycle potential is impressed across the talking conductors of the trunk line TL1, being received through the transformer 362 and amplified through the vacuum tube apparatus to cause a momentary response of the incoming-impulse relay 326. Relay 326 is unable to operate incoming repeating relay 311 at this time, because relay 311 is disconnected at the inner left-hand armature of answering-supervisory relay 317. Relay 321 will most likely restore occasionally during conversation responsive to a restoration of incoming-impulse relay 326, and relay 322 may make momentary responses as it tends to operate through the resting 65 contact of the armature 326 before relay 321 can restore responsive to the opening of its circuit by relay 326. Any such momentary response of relay 322 at this time causes no harmful result, however, as the talking circuit is now complete 70 through the lower right-hand armature of the answering supervisory relay 302 independent of the path through the upper armature of "break" timing relay 322. Incoming-signal relay 323 cannot become operated unless the incoming impulse 75

relay 326 is deenergized and reenergized responsive to successive received impulses of 1000-cycle current occurring in the neighborhood of sixty times a second. This condition, of course, rarely if ever obtains during conversation.

Disconnect supervision

It will be assumed that the called subscriber is the first to replace his receiver when the conversation is terminated, whereupon the repeater in the distant exchange causes a disconnect-supervisory impulse to be transmitted back over the trunk line TL1 to the repeater IR1. This impulse is similar to the answering supervisory impulse, and operations similar to those above described therefore take place again.

At this time, the deenergization of signal-repeating relay 309 under the control of incoming-signal relay 323 results in the closure of a circuit through the inner lower armature of the operated cut-through relay 305, and the upper armature of the operated answering-supervisory relay 302, for disconnect-supervisory relay 301. Two-step relay 301 therefore operates through its first step to close its locking circuit, responsive to the impulse, and it operates completely through both windings in series upon the termination of the impulse.

Upon operating fully, relay 301 opens the locking circuit of answering-supervisory relay 302, whereupon relay 302 restores, thereby reversing the current flow in the calling line to normal direction to give disconnect supervision in case (for example) the calling line is a measured service line or the line is one extending from an operator's switchboard. Relay 301 restores now as it is unlocked at armature 359.

Releasing the established connection

When the calling subscriber at substation SS1, Figs. 1 and 3, replaces his receiver at the end of the conversation, line relay 303 restores and closes a circuit at its inner armature through the operated armature 371 for the outgoing series relay 315. As before, series relay 315 operates to break the circuit over conductor 396 for transfer relay 325 and to close a circuit for preparing relay 313. Preparing relay 313 as before described operates cut-off relay 320. At this time, the grounding of release trunk conductor 362 by cut-off relay 320 is of utility in maintaining the trunk line guarded at this end until the releasing impulse has been completely transmitted and the relays of the impulse repeater have been allowed sufficient time to return to normal condition.

With line relay 303 in deenergized condition, ground potential from the grounded conductor 397 is extended, at the lower armature of line relay 303 through armature 376 of the operated pulse-timer relay 316, to the dial-out relay 314. Relay 314 operates and (pursuant to transmitting a prolonged releasing impulse) connects the branch conductors 393 and 394 to the conductors of the trunk line TL1. At this time, transfer relay 325 is deenergized and 1000-cycle current is therefore transmitted to the grid element of the power amplifier tube 336, whose plate element is connected to the primary winding of outgoing transformer 363.

Since transfer relay 325 is operated over conductor 395, through register 379, the right-hand terminal of the primary winding of transformer 363 is connected to supply lead 347. An impulse

of 1000-cycle current is therefore transmitted over the trunk line TL1.

A moment later, transfer relay 324 restores responsive to being shunted at the lower armature of dial-out relay 314, and substitutes 60-cycle plate current for the steady plate current over lead 347. As a result during the remainder of the impulse the 1000-cycle carrier current is transmitted modulated by the 60-cycle modulating plate current.

This prolonged releasing impulse endures until release relay 314, cut-through relay 305, and outgoing series relay 315 restore successively. Relay 315 finally removes ground potential at its left-hand armature from conductor 397, thereby opening the circuit of the dial-out relay 314 and terminating the releasing impulse. The removal of ground potential from conductor 397 opens the circuit of relay 316 and permits it to restore, while preparing relay 313 is restored because its circuit is opened at the right-hand armature of relay 315. A moment later cut-off relay 320 restores responsive to the deenergization of preparing relay 313 and finally removes ground potential from release trunk conductor 362 to render the repeater IR1 idle to the selectors having access to it.

Call from exchange B to exchange A

For the purpose of explaining how an incoming call is handled at the repeater IR1, Fig. 3, it will be assumed that a subscriber in either exchange B or exchange C desires to obtain connection with a subscriber in exchange A. It will be assumed further that the trunk line TL1 is seized by way of the impulse repeater IR2, Fig. 1, in exchange B when the digit assigned to the exchange A is dialled.

Seizing the incoming selector

When the trunk line TL1 is seized in exchange B, the repeater IR2 operates in a manner described for the repeater IR1, Fig. 3, to transmit a seizing impulse over the trunk line TL1 to exchange A. This seizing impulse, it will be recalled constitutes a 1000-cycle carrier current completely modulated sixty times a second.

This incoming impulse is received over branch conductors 391 and 392 leading from the talking conductors of the trunk line TL1 to the primary winding of incoming transformer 362, and is repeated thence through the vacuum tubes 336, 337 and 338 to the incoming-impulse relay 326. As before explained, incoming-impulse relay 326 responds to the 60-cycle modulation of carrier current and releases and reoperates at the rate of sixty times a second. As before described, the "make" timing relay 321 is maintained energized during the 60-cycle operation of incoming impulse relay 326 and the "break" timing relay 322 operates and remains operated throughout the seizing impulse. Also, the incoming-signal relay 323 operates through contacts on the "break" timing relay 322 and in parallel with the "make" timing relay 321 so as to shunt relay 209 and cause it to restore.

When relay 309 is thus restored for a short interval, a circuit is closed at the armature of relay 309 through the lower armature and resting contact of cut-through relay 305 and by way of contacts of relays 307 and 308 for the lower winding of the two-step selector-seizing relay 308. Relay 308 therefore operates through its first step and closes its locking circuit at its inner upper armature through the upper armature

of incoming-release relay 309. Relay 307 does not restore at this time because of the shortness of the impulses.

When the seizing impulse has terminated, incoming impulse relay 326 remains operated, and relays 322 and 333 therefore restore; the signal-repeating relay 309 is permitted to reoperate and again close a circuit for incoming release relay 307, as well as to open the initial energizing circuit of two-step relay 308. At this juncture relay 308 operates fully.

Upon operating fully, relay 308 places a ground potential on the incoming release-trunk relay 352 at armature 373 so as to guard the trunk line against seizure in exchange A; it removes relay 308 from under the control of signal-repeating relay 309 at its inner lower armature; it closes a control bridge across the talking conductors leading to the left-hand repeating-coil windings at armature 374; at its lower armature it grounds conductor 399, thereby closing a circuit through resistance element 398 for the polarizing winding of the electro-polarized supervision-control relay 310; and at its upper armature and its middle lower armature it connects the talking conductors extending to the left from the left-hand repeating coil to the corresponding talking conductors extending to the selector S1, Fig. 1.

A controlling bridge now exists across the talking conductors extending to the selector S1 as follows:

From the negative talking conductor of the selector S1 through the upper armature of the operated relay 308 to the upper talking conductor of the impulse repeater IR1, upper left-hand repeating-coil winding, upper armature of the incoming repeating relay 311, armature 374 of relay 308, upper winding of the electro-polarized supervision-control relay 310, lower left-hand repeating-coil winding, and the middle lower armature of relay 308 to the positive talking conductor of the selector S1. The line relay (not shown) of the selector S1 is operated through the control circuit just traced to prepare the selector for operation.

Repeating the incoming dial impulses

When the calling subscriber in the distant exchange operates his calling device in accordance with the first digit in the number locally listed for the subscriber in exchange A, the repeater IR2, Fig. 1, operates in the manner described hereinbefore for repeater IR1, Fig. 3, to transmit impulses of 1000-cycle carrier current at the usual dial frequency, one impulse of 1000-cycle carrier current for each impulse of the series representing the desired digit. When the first impulse of the series is received, the incoming pulse relay 326 restores, opening the circuit of the "make" timing relay 321 and closing a circuit for the "break" timing relay 322. Relay 321 restores and relay 322 operates. Relay 321 restores and opens the circuit of relay 322, so that relay 322 restores, and relay 323 is not operated when relay 326 reoperates; the incoming signal relay 329, therefore, is not affected.

Incoming repeating relay 311 is operated by each restoration of relay 326, through the inner left-hand armature of answering-supervisory relay 317. Upon operating, incoming repeating relay 311 breaks the control bridge across the talking conductors and consequently the circuit of the line relay (not shown) of the selector S1, at its upper armature, while at its lower armature it closes a circuit for incoming series relay 312

which includes the outer armature of the unoperated out-going series relay 315. Relay 312 operates and remains operated throughout the series of incoming impulses.

At its upper armature, relay 312 breaks the talking bridge across the right-hand repeating coil windings to secure a more reliable response of the impulse receiving apparatus for the remainder of the impulse series, while at its inner armature it shunts a resistor around the lower left-hand repeating coil winding and the control winding of relay 310, and at its middle armature it places a shunt around the upper left-hand repeating-coil winding and includes the associated resistor in the circuit so as to improve the condition of the impulsing circuit extending to the selector now being operated.

Each time the incoming-impulse relay 326 is reoperated upon the cessation of an impulse in the series, it opens the circuit of the incoming-repeating relay 311, and permits this relay to restore and reclose the control circuit. As a result of the operation of the incoming-repeating relay 311 under the control of the incoming-impulse relay 326, the line relay of the incoming selector S1 is controlled in the usual manner to position the selector.

It is to be particularly noted that the "make" timing relay 321 restores each time incoming impulse relay 326 falls back under the condition being considered, owing to the relatively slow rate at which relay 326 is deenergized and reenergized. That being the case, relay 322 does not permit relay 323 to respond, as in the previously considered case when the incoming impulse relay 326 is restoring and reoperating at the rate of sixty times a second.

At the end of the series of impulses, the incoming series relay (which remained operated throughout the series of impulses because of its slow releasing characteristics) restores to again place the associated circuits in talking condition.

The series of control operations just described is repeated for each of the subsequent impulse series representing the remaining digits in the desired number.

Answering supervision

When the connection has been set up to the called line, and the called subscriber has responded in the usual manner, the current flow in the conductors outgoing to the local switches through the contacts of the selector-seizing relay 308 is reversed, whereupon the supervision-control relay 310 operates because the current flow in the upper winding of the relay is reversed to agree with the current flow in the polarizing winding. Upon operating, relay 310 shunts the resistor 398 at its inner armature through the resting contact and armature 380 of answering-supervisory relay 317. The shunting of resistor 398 increases the current flow in the lower winding of relay 310 sufficiently to permit the relay to remain operated without regard to the direction of current-flow in the upper winding.

At its lower armature, relay 310 closes a circuit from the grounded conductor 399 through the resting contact and outer left-hand armature of the answering-supervisory relay 317 for the supervisory-repeating relay 319. Relay 319 thereupon operates and closes a circuit for the preparing relay 313 at its inner armature; it shunts the resting contact and armature 380 at its middle armature; and at its outer armature it places a ground potential through the lower

armature of relay 305 on conductor 397 to prepare a locking circuit for pulse-timer relay 316.

When the preparing relay 313 operates at this time, it disconnects the incoming talking conductors; it closes a circuit at its middle lower armature for dial-out relay 314; and at its lower armature it operates the cut-off relay 320.

Transfer relay 325 is deenergized as before described when its circuit over conductor 396 is opened by the preparing relay 313. As a result, an impulse of 1000-cycle current, modulated sixty times a second is again transmitted over the conductors of the trunk line TL2 from the branch conductors 393 and 394 and through contacts of the dial-out relay 314. This impulse of current causes the distant repeater IR2 in exchange B to respond and pass into an answering-supervision state in the manner previously explained in connection with the repeater IR1, Fig. 3.

After a momentary interval, pulse-timer relay 316, whose circuit was closed at the middle lower armature of dial-out relay 314, operates and locks itself to the conductor 397 (grounded at the outer armature of supervision-repeating relay 319).

At armature 376, pulse-timer relay 316 closes a new circuit for the dial-out relay 314 through the lower armature of line relay 303, lower armature and resting contacts of cut-through relay 305, and the left-hand armature of the supervision-repeating relay 319. At armature 378, relay 316 closes a circuit from the grounded conductor 399 and through the right-hand armature and resting contact of disconnect-supervisory relay 318 for the answering-supervisory relay 317. Relay 317 now operates through the associated resistor and at its inner-right-hand armature locks itself directly to conductor 399. At its right-hand armature, it completes an uninterrupted talking bridge; at its inner left-hand armature it disconnects the incoming repeating-relay 311 from in circuit with the resting contacts of the armature of incoming-impulse relay 326; at armature 381 it prepares an operating circuit for disconnect-supervisory-relay 318; at armature 380 it breaks one point in the shunt established around the resistor associated with the polarizing winding of relay 310, and prepares a locking circuit for the disconnect supervisory relay 318; and at its left-hand armature it opens the circuit of the supervision-repeating relay 319 and prepares a new circuit for this relay by way of contacts of relay 318.

Relay 319 now restores and opens the circuit of preparing relay 313 at its inner armature; finally removes the shunt from around resistor 398 at its middle armature; and at its left-hand armature it removes ground potential from conductor 397, thereby opening the locking circuit of pulse-timer relay 316 and the holding circuit of dial-out relay 314. Accordingly, relays 313 and 314 restore to terminate the answering supervisory impulse, and relay 313 again applies ground potential at its middle lower armature to conductor 396 to operate transfer relay 325.

A moment later, pulse-timer relay 316 restores and opens the initial energizing circuit of answering-supervisory relay 317 at armature 378, leaving relay 317 locked up, at its right-hand armature, to the grounded conductor 399.

70 *Disconnect supervision*

When the conversation has ceased, the two subscribers replace their receivers. Assuming that the called subscriber replaces his receiver first, the connector in use causes the current flow in

the conductors leading thereto from the impulse repeater IR1, by way of contacts of selector-seizing relay 309, to be reversed back to normal direction. At this point, the electro-polarized supervision-control relay 310 restores. Upon restoring, relay 310 closes a circuit at its lower armature and through the operated armature 381 for the disconnect-supervisory relay 318. Relay 318 responds and locks itself energized at its middle armature through the operated armature 218 to the grounded conductor 399; it closes an operating circuit for the supervisory repeating relay 319 at its left-hand armature by way of the operated left-hand armature of relay 317; and at its inner left-hand armature it closes a branch circuit for the preparing relay 313. Relay 319 operates and at its inner armature closes an additional circuit for the preparing relay 313; at its middle armature it again shunts 398; and at its left-hand armature it again places ground potential on conductor 397 to prepare a locking circuit for pulse-timer relay 316.

When preparing relay 313 operates at this time, it again operates the cut-off relay 320 at its lower armature, while at its middle lower armature it again disconnects ground potential from conductor 396 to restore transfer relay 325, and it closes a circuit at the said middle lower armature for the dial-out relay 314. As a result, the disconnect supervisory impulse is transmitted back over the trunk line TL1 to the calling exchange as described in connection with the transmission of the answering-supervisory signal.

Pulse timer relay 316 again responds to the closure of its circuit at the middle lower armature of the operated dial-out relay 314. At this time, it locks itself energized at its inner armature to the grounded conductor 397, while at armature 378 it extends the grounded conductor 399 through the operated right-hand armature of disconnect-supervisory relay 318 to the junction of the winding of the answering-supervisory relay 317 and the associated current-supply resistor. Relay 317, being shunted, restores after a slight interval; opens its locking circuit at its right-hand armature; again connects up incoming-repeating relay 311 at its inner left-hand armature; and at its extreme left-hand armature it transfers the supervision-repeating relay 319 from conductor 399 to the front contact of the lower armature of supervision control relay 310, thereby opening the circuit of relay 319. Relay 319 now restores and permits the restoration of relays 316, 313, 314, and 320, together with the reoperation of relay 325.

With the circuits in this condition answering supervision may be given again in case the calling subscriber again removes his receiver, and may be again followed by disconnect supervision.

60 *Releasing the established connection*

As described hereinbefore, the repeater on the originating end of the trunk line TL1 is arranged to transmit a prolonged impulse of 1000-cycle current modulated at a rate of sixty times a second to secure the release of the connection. When this releasing impulse is received, incoming impulse relay 326 of the repeater IR1, Fig. 3, is caused to restore and reoperate at the rate of sixty times a second, in the manner hereinbefore described. Relay 321 is held operated and relay 322 is caused to operate to connect up relay 323, and relay 323 operates to close a shunt circuit to bring about the deenergization of the incoming-signal relay 309. At this time, relay 309 remains

restored for a sufficient length of time to bring about the restoration of the incoming release relay 307.

- When relay 307 restores, it opens an additional point in the circuit over which relay 309 controls the selector-seizing relay 308, and it opens the locking circuit of relay 308. Accordingly, relay 308 restores and frees the selector S1, at the same time removing ground potential from conductor 399 at its lower armature. Relay 309 is not reoperated at this time through the resting contact of the lower armature of incoming-signal relay 309, as it cannot reoperate while the incoming release relay 307 is in deenergized condition.
- At the end of the releasing impulse, relay 326 remains in its operated position shown in the drawings, whereupon relays 322 and 323 restore, while relay 321 remains operated. Signal-repeating relay 309 is again operated in its local circuit responsive to the restoration of relay 323, and it again brings about the operation of the normally energizing incoming release relay 307. When relay 307 reoperates, it finally removes ground potential at the last point from the incoming release-trunk conductor 352 at its upper armature, thereby causing the trunk line TL1 to test idle in the banks of the selector such as S2.

Double seizure of the trunk line TL1

- In the event of double seizure of the trunk line TL1, the action in the impulse repeater IR1, Fig. 3, is similar to the described action of the repeater IR3, Fig. 1. In the event that the seizure of the distant end of the trunk line takes place slightly ahead of the seizure of the trunk line at IR1, Fig. 3, the selector-seizing relay 308 is operated responsive to the selector-seizing impulse to disconnect cut-through relay 305 and to prepare a circuit for busy relay 306, which is closed upon the energization of release relay 304. Busy relay 306 connects up the associated common busy-tone conductor at its upper armature, and at its inner upper armature prepares to permit the local end of the connection to be released when release relay 304 restores responsive to the calling subscriber's replacing his receiver after hearing the busy tone.

Operation of the modified repeater IR1', Fig. 4

- As before mentioned, Fig. 4 shows the repeater IR1', which is a modification of the impulse repeater IT1, Fig. 3. Whereas in the repeater IR1, Fig. 3, a combination of slightly slow-acting relays (321-323) is used to differentiate between an incoming signal impulse (such as a releasing impulse or a supervisory impulse) and a switch operating impulse or an impulse of 1000-cycle voice current, in the modified repeater IR1', Fig. 4, a simple arrangement is employed which makes use of a tuned circuit for the incoming-signal relay 404. Relay 404 is operable under control of detector tube 338 in a resonant circuit which includes the fixed tuning condenser 405 and which resonates at sixty cycles a second. With this arrangement, it is most unlikely that the incoming-signal relay will be operated by anything other than a signal transmitted from the distant exchange over the trunk line TL1 for the express purpose of operating the relay, for the usual dial impulses transmitted over the line are transmitted within the range of from eight impulses a second to twelve impulses a second, and no other spurious current, such as a voice current or a line discharge, is likely to have a carrier fre-

quency of 1000 cycles, modulated at sixty cycles a second.

Completing an outgoing call through repeater IR1'

In order to explain the operation of the modified repeater IR1' it will be assumed first that this repeater is seized by way of conductors 351, 352, and 353 pursuant to an outgoing call over the trunk line TL1 from exchange A to exchange B. It is to be noted that the parts appearing in Fig. 4 which correspond exactly to parts appearing in Fig. 3 have been given the same respective reference characters, so as to facilitate the understanding of the modified arrangement. It will be noted more particularly that the modification consists in removing of relays 320-323 and 326 of Fig. 3 and replacing them with devices 401-404 of Fig. 4, and in replacing the signal repeating relay 309 of Fig. 3 with the signal repeating relay 405, Fig. 4. The remaining parts of Fig. 4 will be found to correspond with the arrangement of Fig. 3.

It is to be noted that the plate circuit supply current of the detector tube 338 in Fig. 4 includes either the retard coil 403 or the incoming-impulse relay 402, depending upon the energized or deenergized condition of the transfer relay 401. Transfer relay 401 is normally deenergized and retard coil 403 is normally in circuit, which condition is maintained throughout an outgoing call, as it is unnecessary to receive any incoming dial impulses when an outgoing call is being made. Transfer relay 401 is operated, however, pursuant to an incoming call (to be later explained) to disconnect the retard coil 403 and substitute the incoming-impulse relay 402.

Upon its seizure, the impulse repeater IR1', operates exactly as explained in connection with the impulse repeater IT1, Fig. 3, to transmit a seizing impulse over the trunk line TL1 to the distant exchange and to repeat the dial impulses over the trunk line, pursuant to the positioning of the switches in the distant exchange.

After the connection has been set up to the desired line and the called subscriber has answered, the hereinbefore-described answering-supervisory impulse, consisting of an impulse of 1000-cycle current modulated by a 60-cycle current, is transmitted back from the called exchange to the calling exchange over the trunk line TL1, and is amplified through the vacuum tubes 336, 337, and detected at the detector tube 338, causing a 60-cycle component to be impressed on the plate current flowing in the plate circuit of the detector tube 338.

As above mentioned, the fixed condenser 405, included in circuit with the incoming-signal relay 404, has a capacity such as to cause the circuit through the incoming signal relay 404 to resonate at sixty cycles a second. As a result, a 60-cycle operating current now passes through the split-core, shaded relay 404, causing this relay to operate and close an operating circuit for signal-repeating relay 405. The signal repeating relay 405 is slightly slow to operate so that it will remain unaffected in the necessarily rare event that incoming-signal relay 404 is momentarily operated responsive to a spurious or stray current of similar characteristics to the signalling current normally employed. Upon operating, relay 405 secures the results described in connection with the release of the signal-repeating relay 309. This result is the operation of the answer-

ing-supervisory relay 302 through its first step when relay 405 responds, and through its second step when relay 405 restores, thereby giving answering supervision to the calling line.

- 5 When the disconnect-supervisory signal is transmitted back over the trunk line TL1 responsive to the receiver being replaced on its switchhook at the called substation, relay 404 is again operated to again operate relay 405, where-
 10 upon the disconnect-supervisory relay 301 is momentarily operated as described hereinbefore to bring about the restoration of answering supervisory relay 302 and thus give disconnect supervision to the calling line.
 15 The release of the established outgoing connection takes place as hereinbefore described in connection with the disclosure in Fig. 3, including the transmission of the prolonged releasing impulse.
 20 *Completing an incoming call through repeater IR1'*

For the purpose of explaining the operation of the modified repeater IR1', Fig. 4, in connection with incoming calls, it will be assumed that the trunk line TL1 is seized in the regular manner at the distant exchange pursuant to a call from exchange B to exchange A. In this event, the usual seizing impulse is transmitted over the 25 trunk line TL1 from the distant exchange to the impulse repeater IR1'. Upon the receipt of this impulse, the 60-cycle component thereof is transmitted through the hereinbefore explained action of the detector tube 338 to the 60-cycle resonant 30 circuit including the incoming-signal relay 404, securing a response of this relay. Relay 404 brings about the operation of the signal-repeating relay 405, whereupon the two-step selector-seizing relay 308 is operated through its first step to 35 close its locking circuit and is subsequently operated through its second step to effect the seizing of the associated selector (when the seizing impulse is terminated and relays 404 and 405 restore). When conductor 399 is grounded at the 40 lower armature of selector-seizing relay 308, upon the complete operation of this relay, a circuit is closed through the right-hand armature and resting contact of answering-supervisory relay 317 for transfer relay 401. Relay 401 thereupon 45 operates and closes the circuit of the incoming-repeating relay 311 at its upper armature, at the same time substituting incoming-impulse relay 402 for the retard coil 403. Incoming impulse relay 402 immediately operates in the plate circuit of the detector tube 338 and opens the circuit 50 of incoming-repeating relay 311 before relay 311 has had time to operate.

It may be pointed out that the retard coil 403 55 preferably has the same electrical characteristics as the incoming-impulse relay 402, so that the frequency to which the circuit of the incoming-signal relay 404 is tuned is not altered by the substitution of incoming-impulse relay 402 for the retard coil 403.

60 When the impulses of 1000-cycle current corresponding to the first digit of the desired number are transmitted over the trunk line TL1 to the impulse repeater IR1' from the distant exchange, the plate current in the detector tube 338 is caused to cease momentarily a corresponding number of times, as hereinbefore described. Each time the plate current ceases, incoming-impulse relay 402 restores and closes a circuit for 65 the incoming-repeating relay 311. Relay 311 is

accordingly operated a number of times corresponding to the desired digit to exercise the described control over the connected selector.

This operation is repeated for each of the subsequent digits of the desired number. 5

It may be mentioned, in passing, that the repeater IR1' transmits answering and disconnect signals back over the trunk line TL1 to the originating exchange in the same manner as explained in connection with the impulse repeater 10 IR1, Fig. 3.

During conversation transfer relay 401 is released by answering-supervisory relay 317 to replace relay 402 with retard coil 403, thereby preventing any response of incoming-repeating 15 relay 311 to voice currents. Relay 311 is, moreover, disconnected by relay 401. Relay 401 again reoperates when answering-supervisory relay 317 is restored pursuant to the disconnect supervisory impulse. 20

Releasing the established connection

When the receiver is replaced at the calling substation, the hereinbefore-described releasing impulse is transmitted from the calling exchange 25 over the trunk TL1 to the impulse repeater IR1'. Since this signal consists of a prolonged impulse of 1000-cycle current interrupted at the rate of sixty times a second, the incoming-signal relay 404 is again operated because of the detecting action 30 of detector tube 338. This time, relay 404 is operated for a sufficient length of time to cause signal-repeating relay 405 to be operated long enough to permit the incoming release relay 307 to restore and bring about the restoration of 35 the selector-seizing relay 308 to cause the automatic switches in the local exchange to release. Transfer relay 401 restores when ground potential is removed from conductor 399 at the lower 40 armature of selector seizing relay 308.

Having described the invention, that which is considered to be new and is desired to be protected by Letters Patent will be set forth in the following claims.

What is claimed is:

1. In a multi-exchange telephone system, a trunk line interconnecting two exchanges and having two normally disconnected branches in one exchange, one branch leading to an automatic switch operable to extend connections from the trunk line, the other branch extending to the trunk line from automatic switching apparatus operable to extend the connection to the trunk line, means associated with the trunk line and operable when the trunk line is seized in the 50 distant exchange for connecting the first-named branch to the trunk line and for preventing seizure of the second branch of the trunk line, and means effective when the second branch of the trunk line is taken for use pursuant to completing a connection therethrough to the trunk line for connecting such branch to the trunk line and for preventing subsequent operation of the means for connecting the first-named branch to the trunk line. 55

2. In a multi-exchange telephone system, an interexchange trunk line having two branches in one exchange normally disconnected from said trunk line, means for seizing one of said disconnected branches pursuant to a call outgoing over said trunk line to the distant exchange, means responsive to such seizure for connecting the seized branch to the trunk line, and means effective to the taking for use of the trunk line in 70 75

the distant exchange pursuant to a call in the opposite direction over the trunk line for connecting the other of said branches to the trunk line.

3. In a multi-exchange telephone system, a trunk line interconnecting two exchanges, said trunk line having a first disconnected branch and a second disconnected branch in each of two exchanges, means in each exchange for seizing the first disconnected branch of the trunk line in such exchange, and means automatically responsive to the seizure of the said first disconnected branch of said trunk line in either exchange for connecting the seized branch to the trunk line in such exchange and for connecting the second branch of the trunk line in the distant exchange to the distant end of said trunk line.

4. In a multi-exchange telephone system, a two-way trunk line interconnecting a first exchange and a second exchange, said trunk line having an incoming branch and an outgoing branch at the first exchange, said branches being each normally disconnected from said trunk line, a line relay bridged across the talking conductors of the incoming branch, an automatic switching apparatus associated with the disconnected outgoing branch, means effective upon the seizure of the incoming branch for operating said line relay, means responsive thereto for connecting the incoming branch to the trunk line, means controlled over said trunk line from the second exchange for connecting the talking conductors of the second branch to the talking conductors of the trunk line and for closing a control bridge across the talking conductors of the trunk line, and means for interrupting said control bridge to cause said automatic switching apparatus associated with the outgoing branch of the trunk line to further extend the trunk line.

5. In a multi-exchange telephone system, an interexchange trunk line having two normally disconnected branches in one of said exchanges, two line relays bridged across said disconnected branches respectively, a line-relay-control bridge associated with the conductors of said trunk line, means locally controlled in the first exchange for connecting the talking conductors of the branch with the talking conductors of the trunk line, means controlled from the distant exchange for connecting the talking conductors of the second disconnected branch to the talking conductors of said trunk line, and means effective only when the second branch is connected to said trunk line for rendering said line-relay-control bridge effective.

55 6. In an impulse correcting repeater arranged to respond to each impulse of a series by transmitting a corrected impulse responsive to the receipt of each incoming impulse of the series, means effective when the incoming impulses are being received at a given frequency for retransmitting corrected impulses of a given length, and means quiescent at said given frequency, but actively effective when the impulses are incoming at a lower frequency for exercising a maximum-limit control over the length of the corrected outgoing impulses.

7. In an impulse correcting repeater arranged to receive a series of incoming impulses and to transmit a corrected outgoing impulse for each incoming impulse received, means in the impulse corrector for delaying the starting of an outgoing impulse until the lapse of a predetermined time following the receipt of the corresponding incoming impulse, and means for terminating the

outgoing impulse responsive to the beginning of the next following incoming impulse.

8. In an impulse correcting repeater arranged to receive a series of incoming impulses and to transmit a corrected outgoing impulse for each incoming impulse received, means in the impulse corrector for delaying the starting of an outgoing impulse until the lapse of a predetermined time following the receipt of the corresponding incoming impulse, means for terminating the transmission of a corrected outgoing impulse responsive to the beginning of the next following incoming impulse, and additional means for terminating the final outgoing corrected impulse of a series.

15 9. In an impulse corrector arranged to receive a series of incoming impulses and to transmit a corrected outgoing impulse for each received incoming impulse, means for starting each corrected impulse a predetermined time following the beginning of the corresponding incoming impulse, and means for terminating each corrected outgoing impulse responsive to the lapse of a predetermined time interval or to the beginning of the next incoming impulse, whichever occurs first.

20 10. In an impulse corrector arranged to respond to a series of incoming impulses to transmit a corrected outgoing impulse for each incoming impulse received, means for regulating the length of each corrected outgoing impulse to a fixed standard which is independent of variation in the length of an incoming impulse within fixed limits, and means for preventing the termination of an outgoing impulse prior to the termination of the corresponding incoming impulse, whereby, when the incoming impulse is of such a length as to greatly exceed the length of the incoming impulses normally received, the length of the outgoing repeated impulse is accordingly increased.

25 11. In an impulse corrector arranged to respond to a series of incoming impulses by repeating a corrected outgoing impulse for each incoming impulse received, means for regulating the length of each corrected outgoing impulse so that it is independent of the length of the corresponding incoming impulse, within fixed limits, and means effective when an incoming impulse exceeds the fixed limits and is of indefinite length for causing the corresponding outgoing impulse to be transmitted as an impulse of a corresponding indefinite length.

30 12. In an inter-exchange telephone system, a trunk line extending from a first exchange to a second exchange, means in the first exchange for transmitting a carrier current over said trunk line to the second exchange and for modulating the carrier current approximately at a given frequency so as to break the carrier current up into a desired number of switch controlling impulses, means at the second exchange responsive to the modulated carrier current for further extending the trunk line in the second exchange to set up a desired connection, means in the first exchange effective when the connection set up is to be released for transmitting carrier current over said trunk line modulated at a substantially higher frequency, additional means in the second exchange selectively responsive to the higher frequency modulating current to effect the release of the extended connection, and means including a series of relays each of which has a slow-acting characteristic for causing the last named means to

respond when the carrier current is modulated at the said higher frequency and to fail to respond when the carrier current is modulated at or near said given frequency.

5 13. In an inter-exchange telephone system, a trunk line extending from a first exchange to a second exchange, means for setting up connections from either of said exchanges to the other by way of said trunk line and for further extending each 10 connection in the distant exchange responsive to control exercised over said trunk line, means in each exchange effective when the connection is set up over said trunk line to the other exchange for transmitting a seizing impulse over said trunk 15 line to the other exchange to prepare for the further extension of the connection in the other exchange, means in each exchange and effective in whichever one is the called exchange for transmitting an answering supervisory impulse back 20 over said trunk line to the calling exchange, and effective subsequently for transmitting a disconnect supervisory impulse back over said trunk line to the calling exchange, a pulse-timer relay in each of said exchanges and associated with such 25 trunk line, and means for operating said pulse-timer relay when the exchange at which it is located is the calling exchange to time the duration of the seizing impulse, and for operating said relay when the exchange in which it is located is the 30 called exchange for operating said pulse-timer relay to time the duration of the answering supervisory impulse and for subsequently operating the relay to time the duration of the disconnect supervisory impulse.

35 14. In a multi-exchange telephone system, an inter-exchange trunk line extending from a first exchange to a second exchange, means in the first exchange for taking said trunk line for use pursuant to a call over said trunk line for completion 40 by way of the second exchange, means in the first exchange for transmitting impulses of voice-frequency current over said trunk line to the second exchange indicative of the destination of the call, impulse translating means in the second 45 exchange including a repeating relay which responds once for each of the said impulses of voice-frequency current transmitted over said inter-exchange trunk line, switching means in the second exchange for completing the connection 50 as indicated by the responses of said repeating relay, and means automatically effective responsive to the call through the established connection being answered or disabling said relay so that it does not respond to voice currents during conversa- 55 tion.

15. In a multi-exchange telephone system, a two-way trunk line interconnecting two exchanges, means for taking said trunk line for use in either exchange and for operating switching 60 apparatus in the other exchange to complete a desired inter-exchange connection by way of said trunk line, a repeating relay in one exchange, means for causing said repeating relay to respond to impulses of voice-frequency current 65 received over the trunk line from the distant exchange to control the operation of switching apparatus in the exchange at which the relay is located, pursuant to making a desired extension of the inter-exchange trunk line, and means 70 for rendering the responses of said repeating relay effectual only when said trunk line is taken for use in the distant exchange.

16. In a telephone system as claimed in claim 15, means automatically responsive to the extended 75 connection being answered for rendering said re-

peating relay non-responsive to voice currents arising during conversation.

17. In a telephone system, a trunk line, means for transmitting voice-frequency impulses over the trunk line, a thermionic valve arranged to operate as a detector and having its input circuit associated with said trunk line to enable it to respond to the voice frequency impulses, means for causing plate current to flow normally through said thermionic valve, and means for so controlling the grid element of the valve that the flow of plate current is prevented throughout the receipt of an impulse of voice-frequency current, and relay apparatus associated with the plate circuit of said detector tube for translating the response of the detector tube into impulses of utility in the setting up of telephone connections.

18. In a multi-exchange telephone system, an interexchange trunk line, a vacuum tube apparatus associated with said trunk line in one exchange, 20 said apparatus including a detector tube arranged to convert a train of voice-frequency impulses into a single impulse of direct current, a plate relay associated with said detector tube and arranged to respond to the direct current impulse 25 occasioned by any train of voice frequency impulses received over said trunk line, a resonant circuit electrically associated with the plate circuit of the detector tube, and a signal relay responsive to current flow in said resonant circuit, 30 whereby said signal relay is operated responsive only to series of voice frequency impulses modulated at the resonant rate of said resonant circuit.

19. In a telephone system, a detector tube associated with a talking circuit, means interposed between the talking circuit and said detector tube for permitting only such voice currents as have substantially a predetermined frequency for reaching the detector tube, said detector tube being arranged to translate each received series of voice current impulses into a single impulse, a signal relay associated with the output circuit of said detector tube, and resonant means interposed between said output circuit and said signal relay 45 for permitting only rectified impulses following each other at approximately a predetermined frequency to reach said signal relay, whereby said signal relay is affected only when currents of a predetermined voice frequency are modulated at 50 a predetermined modulating frequency.

20. In a telephone system, a two-way inter-exchange trunk line, means in one exchange for transmitting signals over said trunk line to the other exchange, means for receiving signals transmitted over the trunk line from the other exchange, a vacuum tube amplifier, and switching means for selectively associating said vacuum tube amplifier with the transmitting means or with the receiving means, depending upon whether signals are to be transmitted or received.

21. In a telephone system, a telephone line, means associated with said telephone line for transmitting signals thereover which are of utility incidental to the desired extension of the telephone line, receiving means associated with said line responsive to signals which may be impressed on said line, a vacuum tube amplifier for amplifying either transmitted or received signals, and selective switching means automatically effective 65 to interpose said amplifier between the line and the receiving means when signals are to be received and for interposing the amplifier between the transmitting means and the line when signals are to be transmitted.

22. In an impulse corrector arranged to respond to a series of incoming impulses by repeating a corrected outgoing impulse for each incoming impulse received, means for starting each repeated impulse responsive to the starting of the original incoming impulse independent of the termination of such original impulse, and means for making
- 5

the termination of the repeated impulse dependent upon the original impulse having terminated, whereby the repeated impulse may be of indefinite duration when the original impulse is of indefinite duration.
